UNITED STATES PATENT OFFICE.

DAWSON M. TAGGART, OF LANCASTER, PENNSYLVANIA, AND FREDERICK J. SCUDDER,
OF LONG ISLAND CITY, NEW YORK, ASSIGNEES TO WESTERN ELECTRIC COMPANY,
INCORPORATED, OF NEW YORK, N. Y., A CORPORATION OF NEW YORK.

MEASURED-SERVICE TELEPHONE SYSTEM.

Application filed December 16, 1920. Serial No. 431,141.

To all whom it may concern:

Be it known that we, DAWSON M. TAGGART and FREDERICK J. SCUDDER, citizens of the United States, residing at Lancaster, in the county of Lancaster, State of Pennsylvania, and Long Island City, in the county of Queens, State of New York, respectively, have invented certain new and useful Improvements in Measured-Service Telephone Systems, of which the following is a full, clear, concise, and exact description.

This invention relates to a telephone system in which connections are established between subscribers' lines by means of mechanical switching devices, and more particularly to a system in which successive calls are registered upon message registers individual to subscribers' lines.

In telephone systems of this character connections between subscribers' lines are established by means of mechanical switching devices, which are controlled in their selective movements by impulse sending mechanism under the control of the subscribers at their respective substations. Following the extension of a connection to a desired subscriber's line, if the connection is successfully established and the desired subscriber responds, mechanism is operated for preparing a charging circuit for charging a call against the calling subscriber upon his individual message register as soon as the conversation over the established connection is terminated, and the calling subscriber releases the connection by restoring his receiver to its switchhook.

When all subscribers' lines terminating in an office of the exchange are individual lines, that is, are provided with but one substation for each line, the registration of successful calls is a comparatively simple matter, and in systems of the general character disclosed the registration may be effected in substantially the manner disclosed in the patent to F. A. Stearn and F. J. Scudder, No. 1,395,977, issued November 1, 1921. In the above mentioned patent a system is disclosed in which a group of subscribers' lines have access to a group of common district selectors through line switches individual to the subscribers' lines. With each district selector is associated call charging mechanism, which is operated upon the suc-

cessful establishment of a connection, and which becomes effective to establish an operating circuit for the calling subscriber's message register upon the release of the established connection. The subscriber's message register is associated with the incoming terminals of the subscriber's line and is operated over a circuit extending through a wiper and bank contact of his individual line switch.

When, however, it is desired to equip certain lines terminating in an office with two substations for supplying two party line service, it is then necessary to associate two message registers with the incoming terminals of each of such lines and to provide discriminating means at the district selector for operating only the register of the calling party. The discrimination is attained by providing a special test condition upon the party line which is placed thereon only when one of the two parties has initiated the call.

The special discriminatory test condition, according to this invention is obtained by placing a ground on the tip conductor of the line through the call-bell at the substation of one of the party line subscribers when the receiver is off the switch hook. Inasmuch as the conductors of a party line might become accidentally grounded by a permanent ground and thus would cause the operation of the discriminatory testing means, regardless of whether one or the other of two parties on the line initiated the call, it is necessary to provide means for detecting the unstandard condition and for preventing the registration of the call upon either of the registers of the substations of the line. It is therefore an object of this invention to provide means for the selective registration of calls initiated upon party lines, upon message registers individual to the respective substations on the line.

A further object of the invention is the provision of means for differentiating between discriminatory testing conditions established upon a calling line by the respective substations thereon and an unstandard condition of the line.

These objects are attained by the provision of a special testing relay associated with the district selector switch, which, dur-

ing the establishment of a connection and prior to the response of the called subscriber, is first operated over a local circuit to ascertain if the relay is in condition to function 5 properly and is then connected to the tip conductor of the calling line. If one subscriber has initiated the call the testing relay does not respond, but if the other subscriber initiated the call the relay responds 10 and operates a switching relay at the district selector to switch the charging circuit from the first subscriber's register to the second subscriber's register.

Upon the response of the called subscriber 15 the call charging mechanism of the district selector is operated to further prepare the charging circuit for operating the selected subscriber's message register upon the termination of the conversation and the release of the connection. As soon as the calling subscriber restores his receiver to the switch hook the release of the connection is initiated and the testing relay is again connected to the tip conductor of the calling 20 line. If the line is in standard condition the testing relay does not function at this time and the call is charged. If the line is un- 25 standard by reason of the connection of a stray ground to either conductor of the line, the testing relay operates at this time, prevents the charging of the call and causes the 30 operation of a selector alarm device associated with the district selector.

The invention may be more readily understood by reference to the following description considered in connection with the accompanying drawings, in which Figure 1 shows one of a group of two party subscribers' lines terminating in a full mechanical 35 office of an exchange and a rotary line switch individual to such line by means of which the subscriber's line may be extended to an idle district selector switch; Figures 2 and 40 3, taken together, show the circuits of a district selector, a sender finder and so much 45 of an office sender as is necessary for an understanding of the invention; Figure 4 shows an incoming selector switch provided with 50 mechanism for applying ringing current to the terminals of a called line, together with the 55 circuits and mechanism for controlling such switch; and Figure 5 shows the mechanism and circuits of a final selector switch and the line of a subscriber to which the selector switch has access. The several figures 60 of the drawing should be arranged, with Figure 1 at the left and the remaining figures in consecutive order.

Description of apparatus.

The calling subscriber's line is provided 65 with two substations, each equipped with a transmitter, receiver and a call bell, and since the line terminates in a full mechanical office each substation is provided with an

impulse dial. The two substations differ from each other in that at one substation the call bell is connected from ground to the ring conductor of the line through a condenser when the receiver is on its switch hook, and 70 from ground directly to the tip conductor when the receiver is off the switch hook, whereas at the other substation the call bell is at all times connected from ground to the tip conductor of the line through a condenser. The substation of called line C, Figure 75 5, is of the usual type.

The calling line terminates in an individual line switch of the well-known step-by-step type, which, through a plurality of 80 wipers, has access to a group of trunk lines terminating in district selector switches. The switch is provided with a stepping magnet for advancing the wipers over terminals of trunk lines in search of an idle district 85 selector switch and for advancing the wipers on around to normal position upon the release of the established connection. Associated with each line switch are two message registers individual respectively to the 90 substations A and B and adapted to be operated over separate circuits extending through wipers of the line switch.

The district selector, incoming selector and final selector switches, shown in Figures 3, 4 and 5, are of the type shown and described in the patent to Craft and Reynolds, 1,123,696, issued January 5, 1915. Each of these switches has a vertically disposed switch shaft provided with five sets 100 of brushes, each brush set having access to a bank of one hundred terminals. For driving the switch shaft upwardly an updrive magnet is provided, which, when energized, presses the switch shaft against a constant- 105 ly driven power drum, and for restoring the switch shaft to normal position a second downdrive magnet is provided, which, when energized, presses the switch shaft against a second constantly driven drum. For de- 110 termining the particular set of brushes on the switch-shaft to be employed, a tripping spindle is provided as described in the Patent 1,123,696 hereinbefore referred to. The final selector switch differs from the other 115 selector switches in being provided with additional means comprising a second up-drive magnet and driving drum for driving the switch shaft upwardly at a higher speed than when driven by the first drum, whereby the switch shaft may be advanced rapidly 120 during its brush selection and group selection movements and more slowly during its terminal selection movement.

The sender finder switch SF and the 125 steering switch shown at RS in Figure 2 are of the well-known step-by-step type, the wipers of which are advanced by stepping magnets. The switch RS functions during a complete half revolution and upon the 130

termination of a connection is left with its wipers in normal position in condition for serving on a new call. The wipers of finder switch SF have no normal position, the 5 wipers resting in contact with the bank terminals last employed by the switch when the switch is not being employed.

The office sender has been only partially disclosed in the dotted rectangle shown in 10 the lower left-hand corner of Figure 2, only such portions of the sender being disclosed as are considered necessary for an understanding of this invention. The circuits of a complete office sender are disclosed in the 15 aforementioned patent to F. A. Stearn and F. J. Scudder, 1,395,977.

For controlling the circuits associated 20 with the several selector switches and the circuits of the office sender, auxiliary 25 switches are provided. These switches may be of the type described in the patent to Reynolds et al, No. 1,127,808, issued February 9, 1915, and known in the art as sequence switches. Each sequence switch 30 comprises a rotatable shaft driven from a constantly operating source of power through a magnetic clutch member and carries a plurality of circuit closing cams, which, at different radial positions of the 35 shaft, cause the closure of a plurality of contacts. The cam contacts associated with each sequence switch are closed only in the positions indicated by the numerals associated therewith, with the exception of the 40 master contacts 251, 301, 401 and 501, associated respectively with the switches 250, 300, 400 and 500, these latter contacts being opened in the positions indicated by the 45 numerals appearing adjacent such contacts and closed in all other positions.

The different pieces of apparatus employed in the system having now been briefly described, it is thought that a clearer 50 understanding of the invention may be had from a description of the method of establishing a call. It will first be assumed that the subscriber at substation A desires a connection with the line of the subscriber at 55 substation C, and that the directory number 50 of the desired subscriber is L1Spennard 9532.

Detailed operation of circuits—Initiation of a call by party A.

55 The calling subscriber upon initiating a call establishes a circuit for the line relay 101 of the trunk hunting switch 100, which circuit may be traced from grounded battery through the right-hand winding of 60 relay 101, the innermost lower armature and back contact of cut-off relay 102, over line conductor 103, through the subscriber's loop at substation A, and thence back over line conductor 104 to ground at the upper armature and back contact of relay 102. Line 65

relay 101 energizes in this circuit and closes a circuit for the stepping magnet 105 of the switch 100, which circuit may be traced from grounded battery through the winding and armature contacts of magnet 105, 70 conductor 106, the lowermost armature and back contact of relay 102, the right-hand armature and front contact of relay 101, conductor 107 and thence to ground through the wiper 108 and the normal contact of the 75 bank to which this wiper has access. The magnet, upon energizing, opens its own circuit and thereupon deenergizes advancing the wipers 108 to 113 inclusive of switch 100 to the second contacts of the respective 80 banks to which they have access. As the second contact which wiper 108 engages is also permanently connected to ground, magnet 105 again energizes and advances the 85 wipers to the third set of contacts leading to the first of the group of trunks to which the switch has access.

If the first trunk of the group is busy there will be a ground potential on the test terminal thereof appearing in the lowermost 90 bank of the switch and the magnet 105 will continue to advance the wipers of the switch until an idle trunk is found upon the test terminal of which battery potential appears. When this battery potential is encountered 95 by the wiper 108, a circuit is closed from battery through the left-hand contacts of sequence switch cam 302 (1) of the district selector switch to which the first idle trunk 100 extends, through the outer left-hand armature and back contact of sleeve relay 200, conductor 114, wiper 108, conductor 107, the left-hand armature and front contact and left-hand winding of relay 101, conductor 115 and thence to ground through both windings of 105 cut-off relay 102. Relay 102 energizes in this circuit and relay 101 is maintained energized over this circuit, through its left-hand winding, after its initial energizing circuit, through its right-hand winding, is opened at 110 the contacts of relay 102. The energization of relay 102 opens the circuit of the stepping magnet at its lowermost armature and back contact and at its upper armature and back contact, and at its upper armature and front 115 contact and uppermost lower armature and front contact, this relay extends the conductors 104 and 103 of the subscriber's line to the wipers 113 and 111 of the switch 100 and thence to the conductors 116 and 117 leading 120 to the selected district selector. Relay 102, at its intermediate lower armature and front contact, also closes a circuit extending from grounded battery through the right-hand winding of sleeve relay 200, conductor 201, 125 the break contact of the left-hand armature of slow releasing relay 325, the lower right-hand contact of sequence switch cam 303 (1 to 2½), conductor 326, the break contacts of the left-hand armature of switching re- 130

lay 202, sleeve conductor 118, wiper 109, winding of marginal message register 119, conductor 120, the intermediate lower armature and front contact of cut-off relay 102 and thence to ground through the upper winding of the cut-off relay. The sleeve relay 200 of the district selector energizes in this circuit but due to its marginal winding the message register magnet 119 does not energize at this time.

For marking the calling line busy to all calls incoming thereto, battery potential is connected to the multiples of test terminal 121 appearing in the banks of all final selectors having access to this line. To accomplish this a circuit is established as soon as the switch 100 leaves normal position, extending from grounded battery through the right-hand winding of relay 124, thence to ground through wiper 112 and the off normal segment 125. Relay 124, upon energizing, connects battery to the test terminal 121 over a circuit extending from grounded battery through the left-hand non-inductive winding of relay 124, the armature and front contact of relay 124 and thence to terminal 121 over conductor 126. The contact between wiper 112 and segment 125 also prepares a circuit extending over conductor 127 to the back contact and right-hand armature of relay 101, preparatory to restoring the finder switch 100 to normal position upon the termination of the connection.

Upon the energization of sleeve relay 200, a circuit is established for the line relay 327 of the district selector switch 350, which circuit extends from grounded battery through the right-hand winding of this relay, the upper left-hand contact of sequence switch cam 304 (1), conductor 328, the lower contacts of sequence switch cam 305, conductor 329 and thence to ground through the front contact and right-hand armature of sleeve relay 200. At its outer left-hand armature and front contact relay 200 connects ground potential to the test conductor 114 of the selected trunk to mark the trunk busy to other line switches, and at the back contact of this armature disconnects the source of battery potential, which, up to the time the selector switch was seized, marked the selector switch as idle. The disconnection of battery potential from test conductor 114 now opens the holding circuit of relay 101 of the subscriber's line switch and this relay deenergizes, the cut-off relay 102, however, being maintained energized over the circuit previously traced extending through the right-hand winding of sleeve relay 200. The deenergization of relay 101 is without effect at this time.

Relay 327, upon energizing, closes a circuit for driving sequence switch 300 out of its normal position and into position 2, this circuit extending from grounded battery

through the winding of the driving magnet of switch 300, conductor 330, the upper left-hand contact of sequence switch cam 306 (1), the inner right-hand armature and front contact of relay 327 and thence to ground through the right-hand contacts of sequence switch cam 307. The sequence switch magnet energizes in this circuit and under the control of master cam 301 drives the sequence switch into position 2, in which position a circuit is closed from grounded battery through the left-hand winding of relay 325, conductor 331, the lower left-hand contact of sequence switch cam 308 (2 to 11) and thence to ground. Relay 325, upon energizing, closes a holding circuit for the sleeve relay 200, extending through the right-hand winding of relay 200, conductor 201, the make contacts of the left-hand armature of relay 325 and thence to the conductor 326 over the upper right-hand contact of sequence switch cam 303 (13/4 to 16), this circuit being maintained through position 16 of the sequence switch or until relay 325 becomes deenergized. Upon reaching position 2 the sequence switch establishes a new circuit for placing ground potential upon test conductor 114, extending from ground through the upper left-hand contact of sequence switch cam 308, conductor 332 and thence to conductor 114, as previously traced, which circuit is maintained through position 18 1/4 of the sequence switch.

As soon as the sequence switch reaches position 13 1/4, a circuit is closed for the stepping magnet 203 of the sender finder SF, extending from grounded battery through the interrupter contacts and winding of magnet 203, conductor 204, the upper left-hand contact of sequence switch cam 309 (13/4 to 2), conductor 333 and thence to ground through the inner right-hand armature and front contact of relay 327 and the right-hand contacts of sequence switch cam 307. A circuit is also closed at this time through the winding of stepping magnet 203, the winding of cut-in relay 205 and thence over conductor 206 to ground at the lower right-hand contact of sequence switch cam 308 (2 to 11). Relay 205 does not energize at this time, however, since its winding is shunted by ground at the armature and front contact of relay 327. As soon as sequence switch 300 leaves position 1, the initial energizing circuit of relay 327 is opened at the upper left-hand contact of sequence switch cam 304, but this relay remains locked up over a circuit extending from grounded battery through its left-hand winding, its left-hand armature and front contact, the upper left-hand contact of sequence switch cam 310 (1 to 6), the lower right-hand contact of sequence switch cam 311 (1 to 2 1/4), conductor 334, test wiper 207 of the sender finder SF, and to ground at busy contacts of the bank

over which this wiper moves. If the wipers of switch SF are at the time standing upon contacts which are connected to circuits extending to an idle office sender, relay 327 5 does not lock up and the circuit previously traced through stepping magnet 203 is immediately opened at the inner right-hand armature and front contact of relay 327 to prevent the advance of the wipers of switch 10 SF. So long, however, as the test wiper 207 of the switch SF encounters contacts upon which busy ground potential exists, the stepping magnet 203 will advance the wipers of the switch until an idle sender is found, 15 when the wiper 207 will find no ground on the contact corresponding to the idle sender and the line relay 327 will thereupon become deenergized. Relay 327, upon deenergizing, opens, at its inner right-hand armature and 20 front contact, the circuit previously traced, extending through the winding of the stepping magnet 203 and closes, at its inner right-hand armature and back contact, a circuit for driving sequence switch 300 out 25 of position 2 and into position 3. This circuit may be traced from grounded battery through the magnet winding of sequence switch 300, conductor 330, the upper right-hand contact of sequence switch cam 306 30 (2), the inner right-hand armature and back contact of relay 327 and thence to ground through the right-hand contacts of sequence switch cam 307.

As soon as relay 327 deenergizes, the shunt 35 around the winding of cut-in relay 205 is removed at the inner right-hand armature and front contact of relay 327, and relay 205 thereupon energizes in series with stepping magnet 203. Since the winding of relay 40 205 is of comparatively high resistance, sufficient current does not flow in this circuit to cause the energization of stepping magnet 203. Relay 205, upon energizing, closes a circuit extending from ground through its 45 front contact and armature 208, over wiper 207 and the contact upon which it is now resting, conductor 209 and thence to grounded battery through the right-hand winding of relay 210 associated with the 50 selected office sender. Relay 210 energizes in this circuit and causes the advancement of the time measure switch, not shown, associated with the office sender in the manner fully set forth in the patent to Stearn and 55 Scudder, hereinbefore referred to, which time measure switch, upon leaving normal position, closes the off normal contact 211. The test contact upon which wiper 207 is now resting is marked with busy ground 60 potential over a circuit which may be traced from off normal contact 211, through the left-hand winding of differential relay 210 and thence over conductor 209, whereby the 65 sender is marked as busy until the office sender has been restored to normal condi-

tion, either following the abandonment of the call or upon the termination of the functioning of the office sender.

With relays 210 and 205 energized, an impulsing circuit is now established from 70 the conductors of the calling line through the winding of the office register stepping relay 212 for enabling the calling subscriber to set the registers, not shown, associated with the office sender in accordance with the 75 designation of the desired line. This circuit may be traced from grounded battery through the armature and front contact of relay 210, conductor 213, wiper 214, the inner right-hand armature and front contact 80 of relay 205, conductor 215, the upper contact of sequence switch cam 313 (2 $\frac{3}{4}$ to 10), trunk conductor 117, wiper 111 of the trunk finder switch 100, the innermost lower armature and front contact of relay 102, line conductor 103, the impulse contacts 130 of the subscriber's calling dial S, thence through the subscriber's substation circuits, line conductor 104, the upper armature and front contact of relay 102, wiper 113 of switch 90 100, trunk conductor 116, the lower contact of sequence switch cam 312 (2 $\frac{3}{4}$ to 10), conductor 335, wiper 216, thence to ground through the winding of stepping relay 212.

The calling subscriber now receives a 95 dialing tone over this circuit in the manner set forth in the aforesaid Patent 1,395,977, and then proceeds to dial the number of the desired line. Under the assumption that the 100 subscriber desires a connection with a subscriber's line C, which line is listed in the directory as LISpenard 9532, the subscriber proceeds to dial the three letters L I S corresponding to the district designation of the district in which the desired line is located, 105 and then dials the four digits representing the number of the line in such district, which number, as assumed, is 9532. The three letters which represent the district code will cause the setting of code registers 110 (not shown) associated with the office sender, which, in turn, control the operation of the sender to control the setting of the district selector switch 350 and the setting of the sequence switch of the district selector for determining the proper talking path 115 through the repeating coil 336 associated with the district selector. The transmission of the impulses corresponding to the number of the desired subscriber's line 9532, causes the setting of the numerical registers associated with the sender to control the sender to govern the setting of the incoming selector switch 450 and of the final selector switch 550, for extending the connection to the desired line in the selected district.

Following the setting of the code registers of the sender, the sequence switch 250, associated with the office sender, is driven into position 2, in the manner set forth in the 120 125 130

aforesaid patent to Stearn and Scudder, for establishing a fundamental circuit extending from the office sender through the winding of relay 327 of the district selector switch for controlling the setting of the district selector. Since at this time the sequence switch 300 of the district selector is in position 3, the fundamental circuit may be traced from grounded battery through 10 the left-hand winding of relay 327, the upper right-hand and lower left-hand contacts of sequence switch cam 310, conductor 337, armature 217 and front contact of relay 205, wiper 218, sequence switch contact 15 219 (2), the armature and back contact of the 0' counting relay 220, the windings of polarized overflow relay 222, the windings of sender stepping relay 221 and thence to ground through the upper left-hand and 20 lower right-hand contacts of sequence switch cam 223 and resistance element 224.

District brush and group selections.

Relay 327 of the district selector switch 25 and stepping relay 221 of the office sender are energized in this circuit. Relay 221, upon energizing, establishes a circuit in the well-known manner for a counting relay of the group of counting relays associated 30 with the sender corresponding to the setting of the code registers, and relay 327 closes a circuit for driving sequence switch 300 of the district selector out of position 3 and into position 4. This circuit extends from 35 grounded battery through the magnet winding of sequence switch 300, conductor 330, the upper left-hand contact of sequence switch cam 306 (3), conductor 333, the inner right-hand armature and front contact of relay 327 and thence to ground through the 40 right-hand contacts of sequence switch cam 307. With the district selector sequence switch 300 in position 4, the initial energizing circuit of relay 327 is opened at the 45 upper right-hand contact of sequence switch cam 310, but relay 327 is maintained energized over the fundamental circuit by a new circuit extending from grounded battery through its left-hand winding, its left-hand armature and front contact and thence 50 through the upper left-hand contact of sequence switch cam 310 (1 to 6) and over the fundamental circuit as previously traced. A circuit is now closed for the up-drive magnet 338 of the district selector, which circuit extends from grounded battery through the winding of magnet 338, the upper right-hand contact of sequence switch cam 309 (4), conductor 333 and 55 thence to ground through the inner right-hand armature and front contact of relay 327 and the right-hand contacts of sequence switch cam 307. Magnet 338, upon energizing, presses the depending portion of the 60 switch shaft 339 against the constantly rotating updrive drum 340, thereby causing the upward movement of the switch shaft.

As the switch shaft of the district selector switch moves upwardly and approaches its first brush tripping position, brush 341 engages the first metallic portion of the commutator segment 342, and a circuit is closed as follows in shunt of the windings of the sender stepping relay 221, which may be traced from grounded battery through 70 the left-hand winding, left-hand armature and front contact of relay 327, the upper left-hand contact of sequence switch cam 310 (1 to 6), the upper right-hand contact of sequence switch cam 311 (3 3/4 to 4), conductor 343, commutator segment 342, brush 341, conductor 344 and thence to ground through the upper right-hand contact of sequence switch cam 314 (9 to 7). Relay 327 is maintained energized over this shunt 75 circuit, but relay 221, being shunted, de-energizes, causing, in the well-known manner, the energization of the counting relay which is paired with the previously energized counting relay. 80

As the switch shaft continues in its upward movement, brush 341 moves into engagement with an insulating portion of the segment 342 and the shunt around the windings of sender stepping relay 221 is removed, whereupon the sender stepping relay again energizes. In this manner, during the upward movement of the switch shaft of the district selector, the stepping relay 221 of the office sender is intermittently energized and deenergized, causing the successive energization of the counting relays associated with the sender. If it be assumed that the No. 2 counting relay was energized upon the initial energization of 105 sender stepping relay 221, then, when the switch shaft of the district selector has advanced to such a position as to position the third set of brushes carried thereby in position to be tripped, the No. 0' counting relay 110 220 will be energized in series with the No. 0 counting relay 225 and will open the previously traced fundamental circuit at its armature and back contact. Counting relay 220 is also instrumental at this time in causing the advancement of the sender sequence switch 250 out of position 2 and into position 4. Upon leaving position 2, all counting relays, which have been energized and locked up over the circuit extending through 115 sequence switch contact 226, become deenergized. 120

As soon following the opening of the fundamental circuit by the No. 0' counting relay 220 as the brush 341 engages the next 125 insulating portion of commutator segment 342, relay 327 becomes deenergized and closes a circuit for driving the district selector sequence switch 300 out of position 4 and into position 5, and opens the circuit 130

previously traced through the updrive magnet 338, thereby arresting the upward movement of the switch shaft 339. The circuit for driving sequence switch 300 into position 5 may be traced from grounded battery through the magnet winding of sequence switch 300, conductor 330, the upper right-hand contact of sequence switch cam 308 (4), the inner right-hand armature and back contact of relay 327 and thence to ground through the right-hand contacts of sequence switch cam 307. With sequence switch 300 of the district selector in position 5 and the sender sequence switch 250 in position 15 4, the fundamental circuit previously traced is again established and relays 327 and 221 again energize. Relay 221 now establishes a circuit through one of the counting relays in accordance with the setting of the code 20 registers, and relay 327 establishes a circuit for driving sequence switch 300 out of position 5 and into position 6, this circuit extending from grounded battery through the magnet winding of sequence switch 300, conductor 330, the upper left-hand contact of sequence switch cam 306 (5), conductor 333 and thence to ground through the inner right-hand armature and front contact of relay 327 and the right-hand contacts of 25 sequence switch cam 307. Upon leaving position 5 sequence switch 300 opens the initial energizing circuit of relay 327, but relay 327 is now maintained energized over the fundamental circuit through the upper left-hand contact of sequence switch cam 310 (1 to 6), and the left-hand armature and front contact and left-hand winding of relay 327.

Upon reaching position 6, the circuit previously traced through the winding of updrive magnet 338 is again established through the upper right-hand contact of sequence switch cam 309 (6), and in the manner previously described the switch shaft 339 is again driven upwardly. Since at this time, however, the tripping spindle 345 has been rotated by the tripping magnet 346, which was energized in position 5 of the sequence switch over a circuit extending from grounded battery through the winding of magnet 346, and to ground through the upper right-hand contact of sequence switch cam 308 (5 to 7), the third set of brushes is now tripped during the initial upward movement of the switch shaft 339, and during the continued upward movement of the switch shaft the tripped set of brushes travel over the contacts of the bank with which they are associated. The remaining four sets of brushes on the switch shaft are not tripped at this time and therefore are functionless.

As the switch shaft continues its upward movement and the tripped set of brushes approaches the first set of terminals in the

first group of trunks to which the set of brushes has access, the brush 347 engages the first metallic portion of commutator segment 348, and a circuit is closed in shunt of the windings of the sender stepping relay 221, which shunt circuit may be traced from grounded battery through the left-hand winding, left-hand armature and front contact of relay 327, the upper left-hand and lower right-hand contacts of sequence switch cam 310, conductor 349, segment 348, brush 347, conductor 344 and thence to ground at the upper right-hand contact of sequence switch cam 314 (9 to 7). Relay 327 is held energized over this circuit, but sender stepping relay 221 deenergizes, causing, upon its deenergization, the energization of a counting relay paired with the counting relay which was energized upon the initial energization of relay 221.

As the brush shaft continues in its upward movement, brush 347 engages an insulating portion of segment 348, and the shunt around the windings of sender stepping relay 221 is opened, whereupon relay 221 re-energizes, causing the energization of the next succeeding counting relay. In this manner, during the continued advancement of the switch shaft, the stepping relay 221 of the sender is intermittently energized and deenergized to energize and lock up successive counting relays. If it be assumed that the subscriber has set the code registers in such a manner as to cause the No. 0 counting relay 225 to become energized upon the initial energization of relay 221, then upon the first deenergization of relay 221 the No. 0' counting relay 220 will become energized in series with relay 225, thereby opening the fundamental circuit and causing the advance of the sender sequence switch 250 from position 4 into position 6. At this time the selected set of brushes of the district selector switch will be positioned upon the lowermost set of terminals of the first group of its associated bank. Upon the advance of sequence switch 250 out of position 4, the locking circuit of counting relays 220 and 225 is opened at sequence switch cam 226.

As soon following the opening of the fundamental circuit by the No. 0' counting relay 220 as the brush 347 engages the next insulating portion of commutator 348, relay 327 becomes deenergized, opening at the front contact of its inner right-hand armature, the previously traced circuit of the updrive magnet 338 to arrest the upward movement of the switch shaft, and closing at the back contact of its inner right-hand armature the previously traced circuit for advancing sequence switch 300 out of position 6 and into position 7.

At the time sequence switch 300 moved into position 6, immediately prior to the

- group selection movement of the selector switch, a circuit was established for advancing the steering switch RS, Fig. 2, out of its normal position 1 and into position 2.
- 5 This circuit may be traced from grounded battery through the armature contact and winding of stepping magnet 230, wiper 231, normal contact 232, conductor 233, conductor 234 and thence to ground through the 70 lower left-hand contact of sequence switch cam 314 (6 to $7\frac{1}{4}$). Stepping magnet 230 energizes in this circuit, battery being maintained connected to its winding over contact 227, wiper 228 and conductor 229, and is 75 held energized until sequence switch 300 leaves position $7\frac{1}{4}$ when magnet 230 de-energizes to advance the wipers of switch RS to the second position contacts.
- With sequence switch 300 in position 7, 80 a circuit is established for relay 327, which may be traced through its right-hand winding, the upper left-hand contact of sequence switch cam 304 (7 to $7\frac{1}{4}$), conductor 328, the lower contacts of sequence switch cam 85 305, conductor 329 and thence to ground through the right-hand armature and front contact of sleeve relay 200. Relay 327, upon energizing, closes a circuit for driving sequence switch 300 out of position 7 and into 90 position 8. This circuit may be traced from grounded battery through the magnet winding of the sequence switch, conductor 330, the upper left-hand contact of sequence switch cam 306 (7), the inner right-hand armature and front contact of relay 327, the upper left-hand contact of sequence switch cam 307 (7 to 8) and thence to ground through the make contacts of the right-hand armature of relay 325. 95
- 40 As soon as sequence switch 300 leaves position $7\frac{1}{4}$, the initial energizing circuit of relay 327 is opened at sequence switch cam 304, but if the first trunk in the group of trunks upon which the brushes 351, 352 and 353 are now standing is busy, a ground potential exists on the test terminal 354 and relay 327 is maintained energized over the circuit extending from grounded battery through its left-hand winding, left-hand 105 armature and front contact, the lower left-hand contact of sequence switch cam 315 ($7\frac{1}{2}$ to 9), the outer right-hand armature and front contact of relay 327, the lower contacts of sequence switch cam 322 (7 to 8), brush 353 and terminal 354, and when sequence switch 300 reaches position 8 a circuit is established for the updrive magnet 338. The circuit of updrive magnet 338 may be traced from grounded battery through the 110 winding of this magnet, the upper right-hand contact of sequence switch cam 309 (8), the inner right-hand armature and front contact of relay 327 and thence to ground through the right-hand contacts of cam 307. 115
- 45 The updrive magnet 338, upon energizing, 120

drives the switch shaft upwardly in search of an idle trunk in the selected group. So long as the test brush 353 encounters the terminals of busy trunks, relay 327 remains locked up. When, however, an idle 70 trunk is encountered, which, it will be assumed, is the trunk terminating in terminals 355, 356, and 357, the locking circuit of relay 327 is opened as no ground potential exists on the test terminal 357 and relay 327 75 deenergizes as soon as the brushes have been properly centered on the bank terminals 355, 356 and 357. Until the brushes are so centered, relay 327 is maintained locked up over a circuit extending through its right-hand winding, the upper right-hand contact of sequence switch cam 304 (8), conductor 358, centering segment 359, brush 360, conductor 344, the lower right-hand contact of sequence switch cam 309 (8), conductor 338, the inner right-hand armature and front contact of relay 327 and thence to ground through the right-hand contacts of sequence switch cam 307. Relay 327, upon deenergizing, opens the previously traced circuit 85 of the updrive magnet 338, thereby arresting the brushes 351, 352 and 353 upon the terminals 355, 356 and 357 of the trunk line extending to the district of the exchange in which the desired line terminates. Relay 327 also establishes the previously traced 90 circuit for driving the sequence switch 300 out of position 8 and into position 9. 95

As soon as sequence switch 300 reaches 100 position $8\frac{1}{2}$, a busy ground potential is placed on the multiples of test terminal 357, over a circuit which may be traced from ground through the upper left-hand contact of sequence switch cam 315 ($8\frac{1}{2}$ to 14 $\frac{1}{2}$), the upper right-hand contact of sequence switch cam 315 (7 to 16), conductor 361, overflow segment 362, brush 363, conductor 364, brush 353 and thence to the multiples of terminal 357. 105

Relay 327 again energizes when sequence 110 switch 300 reaches position 9 over a circuit extending through its right-hand winding, the upper left-hand contact of sequence switch cam 304 (9 to 10), conductor 328, the right-hand contacts of sequence switch cam 305 and thence to ground at the inner left-hand armature and front contact of message charging relay 365. Relay 365 was energized as soon as sequence switch 300 reached position 4 over a circuit extending 115 from grounded battery through its winding, the upper right-hand contact of sequence switch cam 316 (4 to 10), conductor 366, the outer right-hand armature and front contact of relay 205, conductor 235, the upper left-hand contact of sequence switch cam 317 (3 to 10), conductor 367, wiper 236 and thence to ground through the back contact and armature of advance relay 237 and resistance element 238. Relay 327, upon 120 125 130 135

ergizing in the circuit previously traced, closes a circuit through its right-hand armature and front contact for driving sequence switch 300 out of position 9 and into position 10, in which position a fundamental circuit is extended from the office sender through contacts of sequence switch cams 318 and 319 of the district selector to the line relay 421 of the incoming selector switch 450.

10 *Incoming brush or thousands selection.*

The fundamental circuit may now be traced from grounded battery through the right-hand winding of relay 421, conductor 422, the upper right-hand contact of sequence switch cam 402 (1 to 10), the upper left-hand contact of sequence switch cam 402 (1), conductor 423, resistance element 424, the upper contact of sequence switch cam 403 (1 to 10), trunk conductor 419, bank terminal 355 and brush 351 of the district selector switch, the upper right-hand and lower left-hand contacts of the sequence switch cam 318, conductor 368, conductor 337, armature 217 and front contact of relay 205, wiper 218 of the sender finder switch SF, sequence switch contact 219 (6), the armature and back contact of counting relay 220, the windings of relays 221 and 222, the upper contacts of sequence switch cam 223 (6), wiper 239 of the sender finder switch SF, conductor 240, conductor 369, the right-hand contacts of sequence switch cam 319, brush 352 and bank terminal 356 of the district selector switch, trunk conductor 420, the lower contact of sequence switch cam 404 (1 to 10), resistance element 425, conductor 426 and thence to ground at the lower contact of sequence switch cam 405 (1 to 8). The sender stepping relay 221 and the line relay 421 of the incoming selector switch 450 energize in this circuit. Relay 221, upon energizing, establishes a circuit in the well-known manner for a counting relay corresponding to the setting of the thousands register of the sender, which in the case assumed is the No. 4 counting relay. Relay 421, upon energizing, closes a circuit for driving sequence switch 400 out of its normal position 1 and into position 2, this circuit extending from grounded battery through the winding of sequence switch magnet 400, the lower right-hand contact of sequence switch cam 406 (1), the outer left-hand armature and front contact of relay 421, conductor 427 and thence to ground at the lower contact of sequence switch cam 407 (1 to 10). As soon as sequence switch 400 leaves position 1, the initial energizing circuit of relay 421 is opened at the upper left-hand contact of sequence switch cam 402, but relay 421 remains energized over the fundamental circuit through a locking branch of the fundamental circuit which may be traced from grounded battery through the right-hand winding of relay

421, the right-hand contacts of sequence switch cam 402, conductor 428, the right-hand armature and front contact of relay 421, conductor 429, the left-hand contacts of sequence switch cam 408 (1 to 4) and thence over the fundamental circuit as previously traced.

With sequence switch 400 in position 2 a circuit is closed for the updrive magnet 430, which may be traced from grounded battery through the winding of this magnet, the upper right-hand contact of sequence switch cam 409 (2), conductor 431, the outer left-hand armature and front contact of relay 421 and thence to ground at the lower contact of sequence switch cam 407 (1 to 10). Magnet 430, upon energizing, presses the depending portion of the switch shaft 432 against the constantly rotating updrive drum 433, causing thereby the upward movement of the switch shaft. During the upward movement of the switch shaft and as the shaft approaches its first brush tripping position, brush 436 engages the metallic portion of segment 434 of the commutator 435 and a circuit is closed in shunt of the windings of sender stepping relay 221, which circuit may be traced from grounded battery through the right-hand winding of relay 421, the right-hand contacts of sequence switch cam 402, conductor 428, the right-hand armature and front contact of relay 421, conductor 429, the upper left-hand and lower right-hand contacts of sequence switch cam 408, segment 434, brush 436, conductor 437 and thence to ground at the lower right-hand contact of sequence switch cam 410 (7 to 5). Relay 421 is maintained over this shunt circuit but relay 221 is shunted down and deenergizes.

Relay 221, upon deenergizing, causes the energization of the No. 4' counting relay in the well-known manner. As the switch shaft 432 of the incoming selector switch continues in its upward movement, the brush 436 engages an insulating portion of the commutator segment 434, whereby the previously traced shunt circuit is opened and relay 221 again energizes to close the circuit of the No. 3 counting relay. In a similar manner the stepping relay 221 is intermittently energized and deenergized as the switch shaft of the incoming selector switch continues its upward movement, or until the No 0' counting relay 220 becomes energized, when the previously traced fundamental circuit is opened at the armature contacts of relay 220 and the sequence switch 250 of the office sender is advanced out of position 6 and into position 8. When sequence switch 250 leaves position 6 the circuit over which the energized counting relays have been locked up is opened at sequence switch cam 226.

As soon following the opening of the fundamental circuit by the No. 0' counting re-

lay 220 as the brush 436 engages the next insulating segment of the commutator 434, relay 421 becomes deenergized. The switch shaft 432 has now been moved into such a position as to condition the fifth set of brushes thereon to be tripped upon the subsequent upward movement of the switch shaft. Relay 421, upon deenergizing, opens the previously traced circuit extending through the winding of the updrive magnet 430 for arresting the upward movement of the switch shaft and closes at its inner left-hand armature and back contact a circuit for driving the sequence switch 400 out of position 2 and into position 3, this circuit extending from grounded battery through the winding of the driving magnet of the sequence switch, the upper left-hand contact of sequence switch cam 406 (2) and thence to ground at the inner left-hand armature and back contact of relay 421. Upon reaching the position 3 sequence switch 400 closes a circuit for the trip magnet 438 extending from grounded battery through the winding of magnet 438 and thence to ground through the right-hand contacts of sequence switch cam 405. Trip magnet 438, upon energizing, rotates the tripping spindle 439 into such a position as will trip the selected set of brushes upon the subsequent upward movement of the switch shaft 432.

Incoming group selection.

With sequence switch 400 in position 3 and the sequence switch 250 of the office sender in position 8, the previously traced fundamental circuit is again closed. The sender stepping relay 221 and line relay 421 of the incoming selector switch energize in this circuit, relay 221 closing a circuit for a lower counting relay of the group of counting relays associated with the sender, which, in this case, will be assumed to be the No. 2 counting relay. Relay 421, upon energizing, again closes the circuit previously traced for driving the sequence switch 400 out of position 3 and into position 4, and at its right-hand armature and front contact closes the previously traced locking circuit for maintaining itself energized over the fundamental circuit after sequence switch 400 leaves position 3. With sequence switch 400 in position 4 and relay 421 energized; the circuit previously traced through the updrive magnet 430 is again closed and the switch shaft 432 is driven upwardly in its group selection movement.

During the initial upward travel of the switch shaft the fifth set of brushes is tripped by the tripping spindle 439, and during the subsequent upward movement of the switch shaft the tripped set of brushes travel in engagement with the terminals of the bank with which they are associated.

The remaining four sets of brushes not having been tripped are functionless. As the tripped set of brushes on the shaft of the switch approaches the lowermost set of terminals in the first subgroup of terminals of its bank, the brush 441 engages the metallic portion of the commutator segment 440 and a circuit is closed in shunt of the winding of the sender stepping relay 221, which may be traced as follows: from grounded battery through the right-hand winding of relay 421, conductor 422, the right-hand contacts of sequence switch cam 402, conductor 428, the right-hand armature and front contact of relay 421, the upper contacts of sequence switch cam 408, commutator segment 440, brush 441, conductor 437 and thence to ground at the lower contact of sequence switch cam 410 (7 to 5). Relay 421 is maintained energized over this shunt circuit but the sender stepping relay is shunted down and deenergizes.

Upon the deenergization of sender stepping relay 221, the No. 2' counting relay becomes energized in the well-known manner. As the switch shaft 432 continues in its upward movement, the brush 441 engages an insulating portion of segment 440 and the previously traced shunt circuit is opened, whereupon the sender stepping relay 221 again energizes. In this manner the sender stepping relay is intermittently energized and deenergized as the switch shaft 432 continues in its upward movement, until the No. 0' counting relay 220 becomes energized, when the fundamental circuit is opened at its armature contacts and the sender sequence switch 250 is advanced out of position 8 and into position 10. Sequence switch 250, upon leaving position 8, opens the locking circuit over which the energized counting relays are maintained energized at sequence switch cam 226.

As soon following the opening of the fundamental circuit by the No. 0' counting relay 220 as the brush 441 engages the next insulating portion of commutator segment 440, relay 421 deenergizes, opening the circuit previously traced through the winding of the updrive magnet 430, thereby arresting the upward movement of the switch shaft. At its inner left-hand armature and back contact, relay 421 closes the circuit previously traced for driving the sequence switch 400 out of position 4 and into position 5. In position 5 relay 421 is again energized over a circuit extending from grounded battery through its left-hand winding, and thence to ground through the right-hand contacts of sequence switch cam 411. Relay 421 now closes a circuit extending from ground at sequence switch cam 407, and through the outer left-hand armature and front contact of relay 421 for driving sequence switch 400 out of position 5 and into

position 6. Upon leaving position $5\frac{1}{4}$ the initial energizing circuit extending through the winding of relay 421 is opened at sequence switch cam 411, but relay 421 remains energized over a locking circuit extending from grounded battery through its right-hand winding, the right-hand contacts of sequence switch cam 402, conductor 428, the right-hand armature and front contact of relay 421, conductor 429, the right-hand contacts of sequence switch cam 412, and thence through test brush 442 to ground on the test terminal 470 of the first trunk of the group to which the brush set has been moved during the group selection movement of the switch shaft, provided the first trunk of the group is at the time busy.

When sequence switch 400 reaches position 6, if relay 421 is at the time locked up, a circuit is closed as previously traced for energizing the updrive magnet 430 for driving the switch shaft 432 upwardly in its trunk hunting movement. This movement will continue so long as the test brush 442 encounters ground potential on the test terminals of trunks of the group over which this brush moves. When, however, an idle trunk is found, which, it will be assumed, is the trunk terminating in terminals 447, 449 and 451, the locking circuit of relay 421 will be opened since no ground potential exists on the test terminal 451. Relay 421 thereupon deenergizes, opening, at its outer left-hand armature and front contact, the circuit of the updrive magnet 430. To insure, however, that the brushes shall be properly centered on the terminals of the selected idle trunk, relay 421 is locked energized to maintain the circuit of the updrive magnet 430, until the brushes are properly centered, by an additional locking circuit extending from grounded battery through the left-hand winding of relay 421, the upper right-hand and lower left-hand contacts of sequence switch cam 411, conductor 443, the centering commutator segment 444, brush 445, conductor 437, the upper left-hand contact of sequence switch cam 410 (6), conductor 431, and thence to ground through the outer left-hand armature and front contact of relay 421 and the lower contact of sequence switch cam 407.

Upon the deenergization of relay 421, following the centering of the brushes of the switch upon the terminals of the selected idle trunk, the circuit previously traced is closed for driving sequence switch 400 out of position 6 and into position 7. In position 7 relay 421 again energizes in a circuit extending through its left-hand winding and the right-hand contacts of sequence switch cam 411, and again closes the previously traced circuit for driving sequence switch 400 out of position 7 and into position 8, in which position the tip conductor of the incoming trunk cir-

cuit are extended through a contact of sequence switch cams 413. The fundamental circuit is now extended to the final selector switch 550 and may be traced from grounded battery through the upper left-hand contact of sequence switch cam 504 (1 to 10), the right-hand winding of relay 518, the lower left-hand contact of sequence switch cam 503 (1), the lower left-hand contact of sequence switch cam 502 (15 to 6), trunk conductor 517, bank terminal 447 and brush 446 of the incoming selector switch 450, the upper left-hand contact of sequence switch cam 413, resistance element 424, the upper contact of sequence switch cam 403 (1 to 10), thence, as previously traced, over the fundamental circuit through the winding of sender stepping relay 221, and returning through the lower contact of sequence switch cam 404 (1 to 10), resistance element 425, conductor 426, and thence to ground at the lower contact of sequence switch cam 405 (1 to 8).

Upon the extension of connection to the final selector switch, relay 421 of the incoming selector switch, which was energized in position 7 of sequence switch 400, is maintained energized when the sequence switch reaches position 8 over a circuit extending from grounded battery through its right-hand winding, conductor 422, right-hand contacts of sequence switch cam 402, conductor 428, right-hand armature and front contact of relay 421, lower right contact of sequence switch cam 414 (7 to 8), brush 448 and terminal 449 of the incoming selector switch, trunk conductor 519, the upper left-hand and lower right-hand contacts of sequence switch cam 505, resistance element 520, and thence to ground through the lower left-hand contact of sequence switch cam 506 (1 to $8\frac{1}{2}$), this circuit being maintained until the sequence switch 500 of the final selector switch leaves position $8\frac{1}{2}$ following the units selection. Busy ground potential is placed on the multiples of test terminal 451 of the selected trunk over test brush 442 and the lower right-hand and upper left-hand contacts of sequence switch cam 412.

Final brush selection.

Upon the extension of the above traced fundamental circuit to the final selector switch 550 with the sender sequence switch 250 in position 10, the sender stepping relay 221 and relay 518 of the final selector become energized. Sender stepping relay 221, upon energizing, establishes a circuit for the No. 4 counting relay in the well-known manner, it being assumed that the calling subscriber has so set the thousands and hundreds register as to prepare the circuit of the No. 4 counting relay.

Relay 518, upon energizing, establishes a circuit for relay 521, which may be traced from grounded battery through the left-hand

winding of this relay, conductor 522, the upper left-hand contact of sequence switch cam 507 (1), conductor 523, the left-hand armature and front contact of relay 518, and 5 thence to ground through the upper contact of sequence switch cam 508 (1 to 11). Relay 521 energizes in this circuit and at its left-hand armature and front contact closes a locking circuit for itself extending from 10 grounded battery through its left-hand winding, through the armature and back contact of test relay 524, the left-hand armature and front contact of relay 521, sleeve conductor 525 of the trunk circuit extending to 15 the final selector switch 550, bank terminal 451 and brush 442 of the incoming selector switch, and thence to ground at sequence switch cam 412. Relay 521, upon energizing, closes a circuit for driving sequence switch 20 500 out of its normal position into position 2, which circuit may be traced from grounded battery through the winding of magnet 500, through the lower contacts of sequence switch cam 509, and to ground at the right-hand armature and front contact of relay 521. When sequence switch 500 moves out of 25 position 1, the initial energizing circuit of relay 518 is opened at the lower left-hand contact of sequence switch cam 503, but relay 518 is maintained energized over the fundamental circuit by reason of a locking circuit 30 extending from grounded battery through the upper left-hand contact of sequence switch cam 504, the right-hand winding of relay 518, the lower right-hand contact of sequence switch cam 510 (15 to 10), the right-hand armature and front contact of relay 518, the lower right-hand contact of sequence switch cam 503 (1 to 6), and thence through 35 the left-hand contact of sequence switch cam 502, and over the fundamental circuit as previously traced. Relay 518 also closes a circuit as soon as sequence switch 500 reaches position 2, which may be traced from grounded 40 battery through the winding of the high speed updrive magnet 526, the upper right-hand contact of sequence switch cam 511, (2), conductor 523, left-hand armature and front contact of relay 518, and thence to ground at 45 the upper left-hand contact of sequence switch cam 508. Magnet 526, upon energizing, presses the depending portion of the switch shaft 527 against the constantly rotating high speed drum 528, thereby causing 50 the switch shaft to be moved upwardly at a high speed in its brush selection movement. During the upward movement of the switch shaft and as the brush shaft approaches its first brush tripping position, brush 532 engages the metallic portion of the commutator segment 530 of the commutator 531 and a circuit is closed in shunt of the windings of the sender stepping relay 221, which may be 55 traced from grounded battery through the upper left-hand contact of sequence switch cam 504 (1 to 10), the right-hand winding of relay 518, the lower contact of sequence switch cam 510 (15 to 10), the right-hand armature and front contact of relay 518, the lower right-hand contact of sequence switch cam 503 (1 to 6), the upper right-hand contact of sequence switch cam 502 (1% to 2), conductor 529, commutator segment 530, brush 532, conductor 533, and thence to 60 ground through the upper left-hand contact of sequence switch cam 506 (13 to 11). Relay 518 is maintained energized over this shunt circuit but sender stepping relay 221 is shunted down and becomes deenergized. Upon the first deenergization of sender 65 stepping relay 221, the counting relay paired with the counting relay, which was energized upon the initial energization of relay 221, in this case the No. 4' counting relay becomes energized and locks up in the well-known manner. As the switch shaft 527 of the final selector switch continues in its upward movement, brush 532 engages an insulating portion of the commutator segment 530, and the previously traced shunt 70 circuit is opened, whereupon the sender stepping relay 221 again energizes and establishes an energizing circuit for the next succeeding counting relay No. 3. In this manner, as the switch shaft continues in its upward movement, the sender stepping relay 221 intermittently energizes and deenergizes, thereby energizing the counting relays of the sender in succession until the No. 0' counting relay 220 becomes energized, 75 when the previously traced fundamental circuit is opened at the armature contacts of counting relay 220 and a circuit is established for advancing the sender sequence switch 250 out of position 10 and into position 12. When the sequence switch 250 leaves position 10, the circuit extending over the contact of cam 226, over which the energized counting relays were maintained locked up, is opened and these relays de- 80 energize. As soon following the opening of the fundamental circuit by the No. 0' counting relay 220 as the brush 532 engages the next insulating portion of commutator segment 85 530, relay 518 becomes deenergized, opening the previously traced circuit of the up-drive magnet 526 and closing a circuit for advancing the sequence switch 500 out of position 2 and into position 3. The circuit of sequence switch 500 may be traced from grounded battery through the magnet winding of sequence switch 500, the upper right-hand contact of sequence switch cam 512, the left-hand armature and back contact of relay 518, and thence to ground through the upper 90 left-hand contact of sequence switch cam 508. The fifth set of brushes has now been posi- 95 100 105 110 115 120 125

tioned with relation to the tripping fingers on the tripping spindle 534, so that upon a subsequent upward movement of the switch shaft this set of brushes will be tripped for engagement with the bank of one-hundred terminals with which this brush set is associated. To cause the tripping of this set of brushes the trip magnet 535 is energized over a circuit extending from grounded battery through the trip magnet 535, and thence to ground at the lower right-hand contact of sequence switch cam 506 (3 to 5), as soon as sequence switch 500 reaches position 3.

15 *Final group or tens selection.*

When sequence switch 500 reaches position 3, the energizing circuit of relay 518 is again established over the fundamental circuit as previously described, and relay 518 and stepping relay 221 of the office sender again energize. Sender stepping relay 221, upon energizing, establishes a circuit for the No. 3 counting relay, it being assumed that the calling subscriber has set the hundreds numerical register in such a position as to condition the circuit of the No. 3 counting relay for completion upon the initial energization of the sender stepping relay 221 during the group selection movement of the final selector switch.

Relay 518, upon energizing, again closes the previously traced circuit for driving the sequence switch 500 out of position 3 and into position 4. With sequence switch 500 in position 4 the previously traced circuit for the updrive magnet 526 is again established at the left-hand armature and front contact of relay 518. Relay 518 also establishes the previously traced locking circuit for itself extending through its right-hand armature and front contact for maintaining itself energized over the fundamental circuit after sequence switch 500 leaves position 3 and opens the initial energizing circuit at the lower left-hand contact of sequence switch cam 503 (3). The high speed updrive magnet 526, upon energizing, again drives the switch shaft 527 upwardly in a group selecting movement. During the initial portion of this movement the fifth set of brushes is tripped by the tripping spindle 534 and during the remainder of the group selection movement the tripped set of brushes travel upwardly in contact with the terminals of the bank with which the brush set is associated. The remaining four sets of brushes not having been tripped are functionless at this time. As the brush shaft 527 approaches the lowermost set of terminals in the bank, brush 538 engages a conducting portion of the commutator segment 537 and a circuit is established in shunt of the windings of the sender stepping relay 221, which may be traced from

grounded battery through the left-hand contact of sequence switch cam 504 (1 to 10), the right-hand winding of relay 518, the lower right-hand contact of sequence switch cam 510 (15 to 10), the right-hand armature and front contact of relay 518, the right-hand contacts of sequence switch cam 503, conductor 536, commutator segment 537, brush 538, conductor 533, and thence to ground at the upper left-hand contact of sequence switch cam 506. Relay 518 is maintained energized in this shunt circuit but sender stepping relay 221 is shunted down and deenergizes, whereupon a circuit is established in the well-known manner for 80 the No. 3' counting relay.

As the switch shaft 527 continues in its upward movement, the brush 538 engages an insulating portion of the commutator segment 537 and the previously traced shunt circuit is opened, whereupon the sender stepping relay 221 again energizes and now establishes in the well-known manner a circuit for the No. 2 counting relay. In this manner, as the switch shaft 527 continues in its upward movement, the sender stepping relay 221 is intermittently energized and deenergized, thereby energizing the counting relays of the sender in succession, until the No. 0' counting relay 220 becomes energized, 95 when the fundamental circuit is opened at the armature contacts of relay 220 and a circuit is established for driving the sender sequence switch 250 out of position 12 and into position 14. When the sender sequence switch leaves position 12 the circuit over which the energized counting relays are maintained locked up is opened at sequence switch cam 226.

As soon following the opening of the fundamental circuit by the No. 0' counting relay 220 as the brush 538 engages the next insulating portion of commutator segment 537, the holding circuit of relay 518 is opened and relay 518 becomes deenergized. Relay 518, upon deenergizing, opens the circuit of the updrive magnet 526 and closes the circuit previously traced for driving sequence switch 500 out of position 4 and into position 5. In position 5 the fundamental circuit extending through the winding of stepping relay 221 and the right-hand winding of relay 518 is again established and relay 518, upon energizing, closes the previously traced locking circuit for itself and establishes a circuit for driving sequence switch 500 out of position 5 and into position 6.

Final units selection.

With sequence switch 500 in position 6 a 125 circuit is established for the low speed updrive magnet 539, which may be traced from grounded battery through the winding of magnet 539, the lower left-hand contact of sequence switch cam 507 (6), conductor 523, 130

the left-hand armature and front contact of relay 518, and thence to ground at the upper left-hand contact of sequence switch cam 508. The low speed updrive magnet 539, 65 upon energizing, presses the depending portion of the switch shaft 527 against the constantly rotating low speed drum 540, thereby causing the upward movement of the switch shaft in its units selection movement.

10 As soon as the switch shaft 527 starts in its upward movement the commutator brush 532 engages a conducting portion of commutator segment 530, whereupon a circuit is closed in shunt of the windings of the sender 15 stepping relay 221, which may be traced from grounded battery through the left-hand contact of sequence switch cam 504 (1 to 10), the right-hand winding of relay 518, the lower right-hand and upper left-hand contacts of sequence switch cam 510, and thence to ground 20 switch cam 510 (15 to 10), the right-hand armature and front contact of relay 518, the lower right-hand contact of sequence switch cam 503 (1 to 6), the upper right-hand contact of sequence switch cam 502 (5 $\frac{1}{4}$ to 6), 25 conductor 529, commutator segment 530, brush 532, conductor 533, and thence to ground through the upper left-hand contact of sequence switch cam 506 (13 to 11). Relay 518 is maintained energized in this circuit but sender stepping relay 221, being 30 shunted down, deenergizes.

The sender stepping relay 221 of the office sender, upon energizing in the fundamental circuit with the sender sequence switch in position 14, establishes a circuit for the No. 2 counting relay, it being assumed that the calling subscriber has set the units register of the sender in a position to condition the No. 2 relay for operation. Upon the 35 first deenergization of relay 221, the circuit of the No. 2' counting relay is established in the well-known manner. As the final selector switch shaft continues in its upward movement, brush 532 engages an insulating portion of segment 530 and the previously 40 traced shunt circuit is opened, whereupon sender stepping relay 221 again energizes, establishing, in the well-known manner, the energizing circuit of the No. 1 counting relay. In this manner, as the switch shaft moves upwardly, the sender stepping relay 45 221 is intermittently energized and deenergized until the No. 0' counting relay 220 becomes energized when the fundamental circuit is opened at its armature and back contact and a circuit is closed for advancing sequence switch 250 out of position 14 and into 50 position 16.

As soon following the opening of the fundamental circuit by the No. 0' counting relay as brush 532 engages the next insulating portion of the commutator segment 530, relay 518 becomes deenergized, opening the previously traced circuit of the low speed

updrive magnet 539, and closing the previously traced circuit for advancing sequence switch 500 out of position 6 and into position 9.

The brushes of the final selector switch 550 have now been positioned upon the terminals of the desired line and sequence switch 500, upon reaching position 8 $\frac{3}{4}$ closes a circuit for reenergizing relay 518, which circuit may be traced from grounded battery through the left-hand contact of se- 70

quence switch cam 504 (1 to 10), the right-hand winding or relay 518, the lower right-hand and upper left-hand contacts of se- 75

quence switch cam 510, and thence to ground at the right-hand armature and front contact of relay 521. Relay 518, upon energizing, closes a locking circuit for itself ex- 80

tending from grounded battery through its right-hand winding, the lower right-hand contact of sequence switch cam 510, the right-hand armature and front contact of relay 518, and thence to ground through the upper contacts of sequence switch cam 513. This locking circuit will be maintained 85

through position 10 of sequence switch 500. Relay 518, upon energizing, also closes a circuit as previously traced for driving se- 90

quence switch 500 out of position 9 and into position 12. When the sequence switch reaches position 10 a new holding circuit 95

is established for relay 518, extending from grounded battery through the left-hand winding of relay 518, the lower right-hand contact of sequence switch cam 515, (10 to 11), the left-hand armature and front contact of relay 518, and thence to ground at the upper left-hand contact of sequence 100

switch cam 508. Upon reaching position 11 sequence switch 500 establishes a new holding circuit for relay 518, extending from ground through the winding of test relay 524, conductor 541, the upper left-hand contact of sequence switch cam 502 (11 to 13), the lower left-hand contact of sequence switch cam 503 (11 to 13), the right-hand winding 105

of relay 518, the upper right-hand contact of sequence switch cam 510 (11 to 12 $\frac{1}{2}$), the right-hand armature and front contact of relay 518, the right-hand contacts of sequence switch cam 513, test brush 542, and thence to battery on the test terminal of the called line if the called line is busy. If the called line is busy as a calling line this battery potential will be connected to the test terminal 543, as previously described, in connection with the trunk hunting switch 100 through the trunk hunting switch, and if the called line is busy as a called line, battery potential 115

the called line, the lower contacts of the cam corresponding to cam 513 and the test brush of such final selector switch.

5 *Testing the called line—line busy.*

If the called line is busy, relay 518 remains energized when sequence switch 500 reaches position 12 and relay 524 also energizes in the locking circuit traced through 10 the right-hand winding of relay 518. The energization of relay 524 opens the previously traced holding circuit of relay 521, which relay thereupon deenergizes, closing a circuit extending from grounded battery 15 through the magnet winding of sequence switch 500, the lower right-hand and upper left-hand contacts of sequence switch cam 509, and the right-hand armature and back contact of relay 521 for driving the sequence 20 switch 500 out of position 12 and into position 13. When sequence switch 500 leaves position $12\frac{1}{2}$, the test circuit traced through the windings of relay 524 and 518 is opened, but relay 518 remains locked up over a circuit 25 extending through its left-hand winding, the lower right-hand contact of cam 515 (12 $\frac{3}{4}$ to 14), the left-hand armature and front contact of relay 518, and to ground at the upper contact of sequence switch cam 30 508 (12 $\frac{3}{4}$ to 16). When sequence switch 500 reaches position 13, relay 521 is again energized over a circuit extending from grounded battery through its left-hand winding, conductor 522, and thence to ground 35 through the upper right-hand contact of sequence switch cam 506 (13), and locks itself to conductor 525 through the back contact and armature of test relay 524, which deenergized when sequence switch 500 left 40 position $12\frac{1}{2}$. Relay 521, upon reenergizing, closes a circuit for driving sequence switch 500 out of position 13 and into position 14, this circuit extending from grounded battery 45 through the magnet winding of sequence switch 500, the lower contacts of sequence switch cam 509, and thence to ground at the right-hand armature and front contact of relay 521. When sequence switch 500 reaches position 14, a circuit is established 50 for the downdrive magnet 544, which may be traced from grounded battery through the magnet 544, the lower right-hand contact of sequence switch cam 511 (14), conductor 523, the left-hand armature and front contact of relay 518, and thence to ground 55 through the upper left-hand contact of sequence switch cam 508.

Upon the energization of the downdrive magnet 544, the depending portion of the switch shaft 527 is pressed against the constantly rotating downdrive drum 545, thereby causing the downward movement of switch shaft 527 into normal position. When the switch shaft reaches normal position 60 a circuit is established for driving sequence switch 500 out of position 14 and into position 17. This circuit may be traced from grounded battery through the winding of sequence switch magnet 500, the upper left-hand contact of sequence switch cam 512 (3 to 16), conductor 546, normal segment 547 of commutator 531, brush 538, conductor 533, and thence to ground through the upper left-hand contact of sequence switch cam 506. Upon leaving position 14, 70 the locking circuit of relay 518 is opened, but in position 17 a circuit is closed extending from grounded battery through the left-hand winding of relay 518, and thence to ground through the upper left-hand contact of sequence switch cam 515 (17) and through interrupter 548. Relay 518 is intermittently energized in this circuit and at its left-hand armature and front contact intermittently connects a source of busy tone 75 current 549 to the ring conductor 519 of the trunk circuit over a circuit extending from ground through the secondary winding of tone coil 549, the lower right-hand contact of sequence switch cam 508 (17), the left-hand armature and front contact of relay 518, conductor 523, the upper left-hand contact of sequence switch cam 511 (17), resistance 520, and the lower right-hand and upper left-hand contacts of sequence switch 80 cam 505. Tone current is conducted over the trunk circuit extending to the calling subscriber's line since at this time the subscriber's line has become disconnected from the office sender at cams 312 and 313 of the 85 district selector switch, as will be presently described. The circuit of the final selector switch is maintained in this condition until the calling subscriber releases the connection in response to the busy signal in a manner to be described hereinafter.

65 *Testing the called line—line idle.*

If in testing the called line the line is found to be idle, ground potential will be 100 encountered on the test terminal 543, this ground potential being supplied from ground through the windings of the called subscriber's cut-off relay corresponding to relay 102, over a circuit extending through 105 the back contact of the relay corresponding to relay 124, shown in Fig. 1. Therefore, when the test circuit through test brush 542 is established to this idle line, the circuit previously traced through the right-hand 110 winding of relay 518 and the winding of test relay 524 will extend from ground to ground, and relay 518 will therefore become deenergized when sequence switch 500 leaves position 11 and test relay 524 will not become 115 energized. When therefore relay 518 deenergizes it closes a circuit for driving sequence switch 500 out of position 12 and into position 13, this circuit extending from 120 grounded battery through the upper right-hand 125 contact of sequence switch cam 515 and through the upper left-hand contact of sequence switch cam 506 to ground.

hand contact of sequence switch cam 512 (12), the left-hand armature and back contact of relay 518, the lower left-hand contact of sequence switch cam 508 (12), 5 and thence to ground at the right-hand armature and front contact of relay 521. Upon reaching position 13 a circuit is established over the lower contacts of sequence switch cam 509, and the right-hand armature and front contact of relay 521, for driving sequence switch 500 out of position 13 and into position 14, and in position 14 a circuit is established, as previously traced, through the winding of sequence switch 10 magnet 500, the right-hand armature and back contact of relay 518, and thence to ground at the upper left-hand contact of sequence switch contact 508, for driving the sequence switch into the talking position 15, 15 in which position the trunk conductors 517 and 519 are connected respectively to the brushes 552 and 553 over the lower contacts of sequence switch cam 502 and the upper contacts of sequence switch cam 505.

20 Following the units selection movement of the final selector switch and during the testing operation of the switch, the sequence switch 500 moves, as previously described, out of position 6 into position 9, and upon 25 leaving position 8½ opens the circuit previously traced extending over the ring conductor 519 of the trunk circuit and through the winding of relay 421 of the incoming selector switch, thereby causing the deenergization of this relay. Relay 421, upon de- 30 energizing closes a circuit for driving sequence switch 400 out of position 8 and into position 9. This circuit may be traced from grounded battery through the winding of sequence switch magnet 400, the upper left-hand contact of sequence switch cam 406 (8), and thence to ground at the inner left-hand armature and back contact of relay 421. With sequence switch 400 in position 35 9, relay 421 is again connected into the fundamental circuit extending through the windings of the sender stepping relay 221 and the windings of overflow relay 222, but since at this time the winding of relay 421 40 is connected to the ring conductor of the fundamental circuit rather than to the tip conductor, as hereinbefore described, current flowing in the fundamental circuit now flows in a direction reverse to the direction 45 in which it originally flowed. The circuit of relay 421 may now be traced from grounded battery through the right-hand winding of relay 421, the lower contacts of sequence switch cam 415 (9), resistance element 425, the lower contact of sequence 50 switch cam 404 (1 to 10), thence over the fundamental circuit, as previously traced, and returning through the upper contact of sequence switch cam 403 (1 to 10), resistance 55 element 424, the left-hand contacts of se-

quence switch cam 408, and thence to ground through the upper contacts of sequence switch cam 412.

The current now flowing over the fundamental circuit is in such a direction as to 70 energize both the sender stepping relay 221 and the overflow relay 222. Overflow relay 222, upon energizing, establishes a circuit for the advance relay 237, which, at its armature and back contact, opens the previously traced circuit extending through the winding of call charging relay 365, Fig. 3. Relay 365 thereupon deenergizes, opening the circuit of relay 327, which thereupon deenergizes and establishes the previously 80 traced circuit for driving sequence switch 300 of the district selector out of position 10 and into position 11. With sequence switch 300 in position 11, a circuit is now established extending from grounded battery through the left-hand winding of line relay 327 of the district selector switch, the upper right-hand contact of sequence switch cam 310 (11), the lower left-hand contact of sequence switch cam 310 (11 to 14), conductor 337, armature 217 and front contact of cut-in relay 205, wiper 218 of the sender finder switch SF, sequence switch contact 219 (16), the armature and back contact of the No. 0' counting relay 220, the windings of overflow relay 222 and sender stepping relay 221, and thence to ground through the upper left-hand and lower right-hand contacts of sequence switch cam 223 (16). Relays 327 and 221 energize in this circuit, the relay 221 establishing a circuit for a counting relay for controlling the subsequent movement of the sequence switch 300 of the district selector for controlling talking selection. In this case it will be assumed that the No. 0 counting relay has been prepared 95 for operation through the setting of the code registers by the calling subscriber in the manner described in the aforesaid patent to Stearn and Scudder No. 1,375,977. 100

Selection of calling party's message register.

Upon the movement of sequence switch 300 out of position 10, the impulsing circuit, including conductors 335 and 215 over which the calling subscriber set the registers of the office sender, is opened at contacts of sequence switch cams 312 and 313, and the talking conductors 116 and 117 of the district selector trunk are now connected over 115 contacts of these cams to wiper 242 and contact engaged by the wiper 243 of the steering switch RS. Sequence switch 300, upon reaching position 10½, establishes a circuit for advancing the steering switch RS from 120 position 2 to position 3. This circuit may be traced from grounded battery through the back contact, armature and winding of stepping magnet 230, the wiper 231, position 2 contact upon which it is now standing, con- 125

ductor 233, conductor 234, and thence to ground through the lower left-hand contact of sequence switch cam 314 (10½ to 11¼). When the steering switch reaches position 3 a circuit is established for relay 244, which may be traced from grounded battery through the right-hand winding of this relay, conductor 245, contact 246, wiper 247, conductor 248, the lower contact of sequence switch cam 321 (11), and thence to ground at the upper left-hand contact of sequence switch cam 315 (8½ to 14½). Relay 244, upon energizing, establishes a circuit for the test relay 249, which may be traced from grounded battery through the winding of this relay, the left-hand non-inductive winding of relay 244, and thence to ground through the inner left-hand armature and front contact of relay 244. The resistance of the left-hand winding of relay 244, in this instance approximately 4400 ohms is so selected that if relay 249 energizes in series therewith, relay 249 will consequently energize over the line resistance of any calling subscriber's line to which it may be later connected in testing for a discriminatory condition upon such subscriber's line. If relay 249 energizes, a circuit is immediately closed for energizing relay 252, which circuit may be traced from grounded battery through the right-hand winding of relay 252, conductor 253, the right-hand armature and front contact of relay 244, and thence to ground at the armature and front contact of relay 249. Relay 252, upon energizing, establishes a circuit for advancing the steering switch out of position 3 into position 4, this circuit extending from grounded battery through the back contact, armature and winding of stepping magnet 230, wiper 231, the third position contact upon which it is resting, and thence to ground at the outer left-hand armature and front contact of relay 252. Relay 252 performs no other useful function at this time. As soon as the steering switch leaves position 3 the circuit of relay 244 is opened and relays 244, 249 and 252 thereupon deenergize.

If the test relay 249 fails to energize when connected through the left-hand winding of relay 244 upon the routine test to determine the sensitiveness of relay 249, then the steering switch remains in position 3 and relay 244 is maintained energized to connect ground for a sufficient time through its outer left-hand armature and front contact to the circuit extending to the selector time alarm for causing the selector time alarm to operate.

When the steering switch reaches position 3, a circuit is established for the answering supervisory relay 370, which may be traced from grounded battery through the lower left-hand winding of repeating coil

336, winding of relay 370 conductor 371, wiper 243 of the steering switch and its third position contact, and thence to ground through the right-hand non-inductive winding of relay 202. This circuit is maintained 70 through position 8 of the steering switch. Relay 370, upon energizing, establishes a holding circuit for the slow to release relay 325, extending from grounded battery through the left-hand winding of relay 325, 75 the armature and front contact of supervisory relay 370, and thence to ground through the right-hand armature and make contact of relay 325. It is to be noted that the initial energizing circuit of relay 325 was 80 opened at the upper left-hand contact of sequence switch cam 316 when the sequence switch 300 was advanced out of position 10 and into position 11, but relay 325, being slow to release, does not have sufficient time 85 to retract its armatures before the steering switch is advanced to position 3, and the above traced locking circuit is established through the contacts of supervisory relay 90 370.

When the wipers of the steering switch reach position 4 a circuit is established for the stepping magnet 230, extending from grounded battery through the fourth position contact and wiper 228, the winding of magnet 230, wiper 231, and the fourth position contact upon which it is resting, and to ground at the contact controlled by interrupter cam 254 for advancing the steering switch from position 4 to position 5 as soon as the cam 254 makes and interrupts its contact. Upon reaching position 5 the circuit of magnet 230 is again established through the contact of cam 254 and the steering switch continues to advance under the control of cam 254 into position 7. Upon reaching position 7 a circuit is established for magnet 230, extending from grounded battery through the seventh position contact of the switch wiper 228, magnet 230, wiper 231 and the seventh position contact upon which it is resting, conductor 233, conductor 234, and thence to ground at the lower left-hand contact of sequence switch cam 314. The magnet is held energized over this circuit and does not advance the wipers of the steering switch from position 7 until sequence switch 300 leaves position 11¼. 115

During the time that the steering switch is advancing through positions 3 to 5 inclusive, the tip conductor of the subscriber's line is connected to grounded battery for the purpose of charging the line to prevent relay 249 from later operating erroneously due to the line capacity. This circuit may be traced from trunk conductor 116, through the upper contact of sequence switch cam 312 (11 to 14½), conductor 372, wiper 242, contacts 3 to 5 over which this wiper passes, conductor 255, and thence through the left- 120 125 130

hand non-inductive winding of relay 205 to battery and ground. When the steering switch reaches position 6 the winding of the test relay 249 is connected to the tip conductor of the subscriber's line and if, as in the case assumed, the subscriber at substation A of the calling line has initiated the call, the relay 249 will energize over a circuit which may be traced from grounded battery through the winding of relay 249, the sixth position contact of the uppermost bank and wiper 242 of the steering switch, conductor 372, the upper contact of sequence switch cam 312 (11 to 14½), trunk conductor 116, wiper 113 of the line finder switch 100, the upper armature and front contact of cut-off relay 102, line conductor 104, the primary winding of the substation repeating coil 128, switch-hook contact 129, and thence to ground through the calling subscriber's call bell 131. Relay 249 energizes in this circuit and as relay 244 is at this time deenergized, establishes a circuit for the switching relay 202, which may be traced from grounded battery through the left-hand winding of relay 202, conductor 256, the left-hand armature and front contact of relay 205, conductor 257, the right-hand armature and back contact of relay 224, and thence to ground at the armature and contact of relay 249. Relay 202 energizes in this circuit and establishes a locking circuit for itself extending from grounded battery through its left-hand winding, its right-hand armature and front contact, conductor 258, and thence to ground at the right-hand armature and front contact of sleeve relay 200, and at its left-hand armature disconnects the sleeve conductor 118 from the circuit extending to grounded battery through the winding of sleeve relay 200 and connects sleeve conductor 122 to this circuit. The circuit of sleeve relay 200 may now be traced from grounded battery through the right-hand winding of relay 200, conductor 201, the make contacts of the left-hand armature of relay 325, the upper contact of sequence switch cam 303 (13½ to 16), conductor 326, the make contacts of the left-hand armature of relay 202, sleeve conductor 122, bank contact and wiper 110 of the line finder switch 100, the winding of marginal message register magnet 123, conductor 120, the intermediate lower armature and front contact of relay 102, and thence to ground through the upper winding of relay 102. Relay 102 and 200 are maintained energized in this circuit, the magnet 123, being marginally wound, does not energize at this time. The previously traced circuit for test relay 249 is maintained through the wiper 242 of the steering switch until the steering switch leaves position 8.

With the wipers of the steering switch standing on their seventh position contacts,

a circuit is established for advancing the sequence switch 300 of the district selector out of position 11. This circuit may be traced from grounded battery through the magnet winding of sequence switch 300, conductor 330, the upper left-hand contact of sequence switch cam 303 (11 to 14), the inner right-hand armature and front contact of relay 327, the relay 327 being maintained energized at this time over the fundamental circuit extending through the sender stepping relay 221, conductor 373, the seventh position contact upon which wiper 247 of the steering switch is now resting, wiper 247, conductor 248, the lower contact of sequence switch cam 321 (11), and thence to ground at the upper left-hand contact of sequence switch cam 315 (8½ to 14½). Upon reaching position 12 the circuit for advancing the sequence switch is maintained over the right-hand contacts of cam 307 and the switch advances until arrested in either positions 13, 14 or 15 dependent upon the control of the sender with respect to talking selection.

As soon as sequence switch 300 leaves position 11½, the previously traced energizing circuit of stepping magnet 230 of the steering switch is opened and the magnet 230 advances the wipers of the steering switch out of position 7 and into position 8. In position 8 a circuit is established from grounded battery through the armature, contacts and winding of stepping magnet 230, wiper 231 to ground on the eighth position contact upon which it is resting, for advancing the wipers of the steering switch over the ninth position into position 10. In position 10 the trunk conductors 116 and 117 are connected through the wipers 242 and 243 of the steering switch to conductors 372 and 371, and the answering supervisory relay 370 is now maintained energized over the calling subscriber's line loop. It is to be noted that the circuit previously traced for relay 370 is opened at wiper 243 of the steering switch as it passes from position 8 to position 10 in order that a false ground may not be connected to the winding of test relay 249 at this time for falsely operating this relay, but the interval during which the circuit of relay 370 is opened is too short to enable the slow-to-release relay 325 to become deenergized.

As the sequence switch 300 of the district selector passes through position 11½, a shunt circuit is established in shunt of the windings of the sender stepping relay 221, which may be traced from grounded battery through the left-hand winding, left-hand armature and front contact of relay 327, the lower left-hand contact of sequence switch cam 315 (11½), and to ground at the upper contact of sequence switch cam 315. Relay 327 is maintained in this circuit but the

sender stepping relay 221 becomes de-energized, and, in the well-known manner, causes the energization of the counting relay paired with the counting relay which was 5 energized upon the initial energization of sender stepping relay 221 in the talking selection position (16) of the sender sequence switch 250. It will be assumed that for a full mechanical call of the class herein described, 10 the sequence switch 300 of the district selector should be arrested in position 12 and that a circuit over which the No. 0 counting relay 225 was initially energized is prepared in the manner described in Patent 1,395,977. The No. 0' counting relay 220 now energizes and opens the fundamental circuit at its armature and back contact.

As soon following the energization of the No. 0' counting relay 220 as sequence switch 20 300 leaves position 11½, relay 327 becomes deenergized since its locking circuit is now opened at sequence switch cam 315 and its initial energizing circuit over the fundamental circuit was opened upon the energization 25 of counting relay 220. Relay 327, upon deenergizing, opens the driving circuit of sequence switch 300 and the sequence switch is arrested upon reaching position 12.

After sequence switch 300 leaves position 30 11, relay 205 is maintained energized to maintain the fundamental circuit closed through the winding of relay 327 until it is interrupted by the No. 0' counting relay of the office sender, over a circuit which may be traced from grounded battery through the winding of magnet 203, the right-hand winding of relay 205, conductor 206, the lower contact of sequence switch cam 316 (11 to 14), conductor 336, the outer right-hand armature and front contact of relay 205, conductor 235, the upper right-hand contact of sequence switch cam 317 (11 to 16), the outer right-hand armature and front contact of relay 327, and thence to ground at the 45 upper left-hand contact of sequence switch cam 315 (8½ to 14½). As soon as the talking selection is completed that is, the proper talking path through the repeating coil 336 and over the district link conductors has 50 been selected, and relay 327 deenergizes, as above described, this holding circuit for relay 205 is opened and relay 205 deenergizes, thereby opening the circuits controlled thereby extending through the wipers of 55 sender finder switch to the office sender. At the office sender, upon the opening of the fundamental circuit, the sequence switch of the office sender is driven into normal position and the circuits of the sender are 60 stored to normal in the well-known manner.

Upon the setting of sequence switch 300 of the district selector switch into its talking selection position, which, it has been assumed, was position 12, the incoming selector switch functions to apply ringing cur-

rent to the subscriber's line. The sequence switch 400 of the incoming selector is in position 9, and relay 421 is energized over the previously traced circuit through sender stepping relay 221, prior to the advance of 70 the district selector sequence switch into position 11. A circuit is thereupon established for energizing relay 451, which may be traced from grounded battery through the winding of relay 451, the right-hand contact of sequence switch cam 416 (9 to 10), the right-hand armature and front contact of relay 421, conductor 429, and thence to ground through the upper contacts of sequence switch cam 412. Relay 451, upon energizing, 75 closes a circuit for driving sequence switch 400 out of position 9. This circuit extends from grounded battery through the winding of sequence switch magnet 400, the armature and front contact of relay 451, and thence to ground through the left-hand contacts of sequence switch cam 412. Upon leaving position 9 the fundamental circuit previously traced through the winding of relay 421 is opened, and relay 421 deenergizes opening the circuit of relay 451 to arrest sequence switch 400 in position 10.

95 Ringing up the called subscriber.

As soon as sequence switch 400 moves into position 10, if at this time the sequence switch 300 of the district selector has advanced to the selected talking position, a 100 circuit is established for relay 421 extending through the right-hand winding of this relay, through the upper contacts of sequence switch cam 402 (10), conductor 423, resistance element 424, the upper contact of sequence switch cam 403 (1 to 10), trunk conductor 419, bank terminal 355 and brush 351 of the district selector switch, the upper contacts of sequence switch cam 318, the 105 upper right-hand winding of repeating coil 336, the contacts of sequence switch cam 220, (11 to 12½) the windings of polarized call-charging relay 374, the lower right-hand winding of repeating coil 336, the upper contacts of sequence switch cam 319, 110 brush 352 and terminal 356 of the district selector switch, trunk conductor 420, the lower contact of sequence switch cam 404 (1 to 10), resistance element 425, conductor 426, and thence through the lower contact 115 of sequence switch cam 405 (10) to ground. Relay 421 energizes in this circuit but the current is flowing in such a direction that polarized relay 374 does not attract its armature against its lowermost contact for preparing an effective charging circuit. Relay 421, upon energizing, locks up to ground on sleeve conductor 464 over a circuit extending from grounded battery through its left-hand winding, the armature and back 120 125 130

contact of relay 455, the upper left-hand contact of cam 409 (10 to 18), the outer left-hand armature and front contact of relay 421, conductor 427, and thence to conductor 464, through the upper contact of sequence switch cam 407 (2 to 18).

When relay 421 reenergizes, the circuit of relay 451 is again established and the sequence switch 400 is driven out of position 10. When the sequence switch leaves position 10 relay 451 deenergizes opening the circuit through the sequence switch magnet and the sequence switch stops in position 11. With the sequence switch 400 in position 11 the circuit of relay 451 is again established over the upper contact 452 of interrupter cam 453 and the upper left-hand contact of sequence switch cam 416 (11). A circuit is also established in position 11 of sequence switch 400 for applying a steady flow of ringing current to the line of the called subscriber. The circuit over which ringing current is transmitted may be traced from the source of ringing current 454, through the lower left-hand and upper right-hand contacts of sequence switch cam 417, through the ringing cut-off relay 455, the lower contacts of sequence switch cam 402 (11 to 13), conductor 428, the right-hand armature and front contact of relay 421, conductor 429, the lower right-hand contact of sequence switch cam 414 (11 to 14), brush 448 and terminal 449 of the incoming selector switch, trunk conductor 519, the upper contacts of sequence switch cam 505, brush 553 and terminal 557 of the final selector switch, and thence over the called subscriber's line loop through the subscriber's call-bell 558 and back over terminal 559 and brush 552 of the final selector switch, the lower contacts of sequence switch cam 502, trunk conductor 517, bank terminal 447 and brush 446 of the incoming selector switch, and thence to ground at the upper right-hand contact of sequence switch cam 413. (11 to 13½). As soon as relay 451 energizes in position 11 of sequence switch 400, the circuit previously traced through the outer armature and front contact of relay 451 is established for driving sequence switch 400 out of position 11. Upon leaving position 11 relay 451 deenergizes opening the circuit of the sequence switch to arrest it in position 12.

In position 12, relay 451 is energized as soon as a circuit therefor is established over the lower left-hand contact of sequence switch cam 416 (12), and the lower contact 452 of the interrupter cam 453, and upon its energization drives sequence switch 400 out of position 12. Upon leaving position 12 relay 451 again deenergizes and arrests the sequence switch in position 13. In position 13 the source of ringing current 454 is connected over the circuit previously

traced through the interrupter 456 and the right-hand contacts of the sequence switch cam 417, and the called subscriber's bell 558 is operated intermittently until the called subscriber responds. During the application of ringing current to the called subscriber's line, a ringing tone is transmitted back inductively to the calling subscriber's substation from the circuit which may be traced through the lower right-hand winding of repeating coil 458, the upper left-hand and lower right-hand contacts of sequence switch cam 418, condenser 457 and the lower contacts of sequence switch cam 414.

Response of the called subscriber.

In response to the ringing of bell 558, the called subscriber removes his receiver from its switchhook, thereby cutting the call-bell 558 from the line loop and connecting a direct current bridge across the line loop at the substation. Current flowing over the subscriber's line loop from the source 454 now causes the operation of ringing cut-off relay 455, which, upon energizing, opens at its armature and back contact the locking circuit extending through the left-hand winding of relay 421. Relay 421 thereupon deenergizes and opens the circuit over which ringing current was applied to the called line at its right-hand armature and front contact, and at its inner left-hand armature and back contact closes a circuit extending through the upper left-hand contact of sequence switch cam 406, for driving sequence switch 400 out of position 13 and into position 16. When sequence switch 400 passes through position 14, relay 421 again energizes over a circuit extending from grounded battery through its left-hand winding and the right-hand contacts of sequence switch cam 411, and closes a locking circuit for itself extending through its left-hand winding, the armature and back contact of ringing cut-off relay 455, relay 455 having become de-energized as soon as the sequence switch left position 13, the upper left-hand contact of sequence switch cam 409, (10 to 18), conductor 431, the outer left-hand armature and front contact of relay 421, conductor 427, the upper contact of sequence switch cam 407, and thence over the sleeve conductor 464 of the trunk and to ground at sequence switch cam 315 (8½ to 14½), as previously described.

As soon as sequence switch 400 reaches position 14 a direct current path is established through the right-hand windings of repeating coil 458, and thence over the called subscriber's line loop for supplying the called subscriber's line with talking current. This path may be traced from the non-grounded pole of battery through the lower right-hand winding of repeating coil 458, the winding of supervisory relay 459, the upper left-hand

contact of sequence switch cam 414, (14 to 16) the brush 448 and bank terminal 449 of the incoming selector switch, thence over the path previously traced through the called 5 subscriber's substation, and returning over bank terminal 447 and brush 446 of the incoming selector switch, the lower left-hand contact of sequence switch cam 413, (13 $\frac{1}{4}$ to 16) and thence to the grounded pole of battery 10 through the upper right-hand winding of repeating coil 458. Supervisory relay 459 energizes in this circuit and connects the terminals of the central station battery between the left-hand windings of the repeating coil 15 458, in such a manner as to cause current to flow over the trunk line extending between the incoming selector switch and the district selector switch, in such a direction as to energize the polarized call-charging relay 20 374 at the district selector switch to close its alternate contact.

This circuit may be traced from the non-grounded pole of central office battery over conductor 460, the upper left-hand contact 25 of sequence switch cam 405 (11 to 16), conductor 426, resistance element 425, the upper contacts of sequence switch cam 415 (11 to 16), the lower left-hand winding of repeating coil 458, the upper contact of sequence 30 switch cam 404 (11 to 16), trunk conductor 420, bank terminal 356 and brush 352 of the district selector switch, the upper contacts of sequence switch cam 319, the lower right-hand winding of repeating coil 336, the 35 windings of polarized relay 374, the contacts of sequence switch cam 220, the upper right-hand winding of repeating coil 336, the upper contacts of sequence switch cam 318, the brush 351 and terminal 355 of the district 40 selector switch, trunk conductor 419, the lower contact of sequence switch cam 403 (11 to 16), the upper left-hand winding of repeating coil 458, resistance element 424, and thence through the armature and front 45 contact of supervisory relay 459 to ground.

The calling and called subscribers are now connected over a talking circuit with each other, shown on the drawings by heavy lines, the calling subscriber receiving talking 50 current over the circuit previously traced through the left-hand windings of repeating coil 336, and the called subscriber receiving talking current through the right-hand windings of repeating coil 458.

Upon the energization of polarized relay 374 with the sequence switch 300 of the district selector in talking position 12, a circuit is established for relay 252 as soon as 55 interrupter cam 259 rotates to such a position as to close contacts 260. This circuit may be traced from grounded battery through the left-hand winding of relay 252, cam contacts 260, conductor 261, the upper left-hand and lower right-hand contacts of sequence switch cam 324, the alternate con-

tacts of polarized relay 374, the upper contact of sequence switch cam 321 (12 to 14 $\frac{1}{2}$), and thence to ground at the upper left-hand contact of sequence switch cam 315 (8 $\frac{1}{2}$ to 14 $\frac{1}{2}$). Relay 252, upon energizing, 70 locks up through its left-hand winding and its inner right-hand armature and front contact to conductor 261, and at its outer right-hand armature and front contact prepares a circuit for the call charging 75 relay 365, which is closed upon the advance of interrupter cam 259 to a position in which its contacts 260 are opened and its contacts 262 are closed. This circuit may be traced from grounded battery through the winding of relay 365, conductor 263, cam contacts 262, outer right-hand armature and front contact and inner right-hand armature and front contact of relay 252, and thence to ground on conductor 261. Relay 365, upon 80 energizing in this circuit, closes a locking circuit for itself extending through its winding, the upper contacts of sequence switch cam 305, and to ground at its inner left-hand armature and front contact so that 85 its energization is now independent of the contacts of sequence switch cam 324 (1 to 13) and independent of the contacts of relay 374. At its outer left-hand armature and front contact relay 365 prepares a circuit 90 for charging a call on the calling party's message register as soon as the calling party restores his receiver to the switchhook to release the established connection.

Restoration of the established connection.

Following the termination of the conversation both the calling and called subscribers restore their respective receivers to their switchhooks, and the circuit previously traced through the answering supervisory relay 370 is opened at the switchhook contacts at the calling subscriber's substation. This relay, upon deenergizing, opens the locking circuit of slow to release relay 325, which, after an interval, closes a circuit for driving sequence switch 300 out of position 12 and into position 17. This circuit may be traced from grounded battery through the winding of sequence switch magnet 300, the left-hand contacts of sequence switch cam 323, and thence to ground at the normal contacts of the right-hand armature of relay 325. Upon the deenergization of relay 325, the circuit previously traced extending through the winding of sleeve relay 200 and the winding of cut-off relay 102 is opened at the left-hand armature contacts of relay 325, but these 110 relays are maintained energized over a new holding circuit which extends from grounded battery through the right-hand winding of sleeve relay 200, conductor 201, the outer left-hand armature and front contact of relay 365, the lower left-hand contact of se-

quence switch cam 303 (12 to 17), and thence over the circuit previously traced to ground at the winding of cut-off relay 102.

When sequence switch 300 reaches position 14 a circuit is established through the stepping magnet 230 of the steering switch for advancing the wipers of the steering switch from position 10 into position 11, which circuit may be traced from grounded 10 battery through the tenth position contact upon which wiper 228 is resting, wiper 228, conductor 229, winding of stepping magnet 230, wiper 231, the tenth position contact upon which this wiper is standing, conductor 233, conductor 234, and thence to ground at the lower left-hand contact of sequence switch cam 314. This circuit is maintained until the sequence switch leaves position 14½, when stepping magnet 230 deenergizes, advancing the wipers to position 11. In position 11 the talking circuit, extending through wipers 242 and 243, is still maintained in order that a tone signal may be transmitted to the calling subscriber 15 in case the district selector switch has failed to find an idle trunk extending to an incoming selector switch and has therefore moved to its overflow position. This operation of the district selector will be described hereinafter. When sequence switch 300 passes position 16, the previously traced circuit for magnet 230 is again established, and when the sequence switch leaves position 16½, the stepping magnet 230 advances 20 the wipers of the steering switch from position 11 to position 12, where, under the control of the contact of interrupter 254, the stepping magnet 230 advances the wipers of the steering switch to position 16.

40 While the wipers of the steering switch are passing over positions 12 and 13, the tip conductor of the calling subscriber's line is connected over the wiper 242, conductor 255, and the left-hand non-inductive 45 winding of relay 205 to charge the subscriber's line, and when passing over positions 14 to 16, the testing relay 249 is again connected to the tip conductor of the calling line to test for an unstandard condition of 50 the line.

If the calling line is in standard condition no ground is connected at this time to the tip conductor of the calling line, since the calling subscriber has restored his receiver to the switchhook and has thereby disconnected the ground connection through call bell 131, as previously described. If, however, the line is in unstandard condition and either the ring or tip conductors are 55 permanently connected to ground through a stray ground connection, the test relay 249 will become energized at this time. In order that the test may be made both on the tip and ring conductors, the tip and ring conductors are bridged together at this time 60

over a circuit extending from conductor 116 through the upper contact of sequence switch cam 312 (17), the right-hand armature and front contact of charging relay 365, conductor 215 and to conductor 117 through 70 the upper contact of sequence switch cam 313 (17).

If the test relay 249 operates on this second test a holding circuit is established for relay 252 for maintaining this relay energized when the steering switch reaches position 16. Relay 252 was operated over a local circuit while the steering switch was passing from position 8 to position 15, which may be traced from grounded battery 80 through its right-hand winding, contacts 8 to 15 over which the wiper 247 passes, wiper 247, conductor 248, the lower contact of sequence switch cam 321 (16 to 18), and thence to ground at the upper contact of sequence switch cam 315 (16 to 18). The holding circuit for relay 252 may be traced from grounded battery through its right-hand winding, the left-hand armature and back contact of relay 205, the right-hand armature and back contact of relay 244, and thence to ground at the armature and front contact of relay 249. With relay 252 operated when the steering switch reaches position 16, the steering switch is arrested in 90 position 16 and a circuit is established to the selector time alarm extending from ground on conductor 248, wiper 247, the sixteenth position contact upon which the wiper rests and over conductor 264 to the selector time 100 alarm.

The operation of the selector time alarm warns the switchboard attendant that an unstandard condition obtains on a connection which has been established through the 105 particular district selector switch with which the time alarm is associated. The operation of relay 249, at this time, prevents the registration of the call upon the message register of either of the parties on the 110 calling line, and therefore prevents the registration of a call on the register of the party A when the party A may not have been the calling party.

If the test relay 249 does not operate on the second test, relay 252 will not be held energized when the steering switch reaches position 16 and the steering switch will therefore be advanced out of position 16 by a circuit extending from grounded battery 115 through the armature contacts and winding of stepping magnet 230, wiper 231, the position sixteen contact upon which it is resting, and to ground at the outer left-hand armature and back contact of relay 252. When the wipers of the steering switch reach position 17 they are advanced into position 20 through the operation of interrupter cam 254 in the manner previously described.

When the steering switch reaches position 120

16 and relay 252 deenergizes with sequence switch 300 in position 17, a circuit is established for applying booster battery current over the previously traced circuit extending 5 through the windings of message register magnet 123 and cut-off relay 102. This circuit may be traced from grounded booster battery 399 through the lower left-hand and upper right-hand contacts of sequence switch 10 cam 324 (17), conductor 375, the inner left-hand armature and back contact of relay 252, the inner left-hand armature and front contact of relay 200, the left-hand non-inductive winding of relay 200, conductor 201, and thence over the circuit previously traced 15 to ground at the winding of cut-off relay 102. The current now flowing over this circuit is of sufficient strength to energize the marginal message register 123, which, in 20 the well-known manner, registers a call against the calling party.

During the advancement of the wipers of the steering switch from position 16 to position 20, this booster battery is applied for 25 operating the message register, the movement of the steering switch allowing sufficient time for the operation of the register. When the steering switch reaches position 20 a circuit is established for relay 327 of the district selector, which may be traced from grounded battery through the right-hand winding of this relay, the lower contact of sequence switch cam 304 (17), position 30 contact upon which wiper 247 is resting, wiper 247, conductor 248, and thence 35 to ground as previously traced at the upper left-hand contact of sequence switch cam 315. Relay 327, upon energizing, closes a circuit which may be traced from grounded 40 battery through the winding of sequence switch magnet 300, conductor 330, the upper left-hand contact of sequence switch cam 306 (17), the inner right-hand armature and front contact of relay 327, and thence to ground at the right-hand contacts 45 of sequence switch cam 307, for advancing sequence switch 300 into position 18, in which position the booster battery is disconnected at sequence switch contact 324. 50 With sequence switch 300 in position 18 a circuit is established for advancing the steering switch into position 21, which circuit may be traced from grounded battery through the armature, contacts and winding 55 of stepping magnet 230, wiper 231, the position 20 contact with which it is associated, conductor 265, and thence to ground through the lower right-hand and upper left-hand contacts of sequence switch cam 315. 60 With sequence switch 300 in position 18 and the steering switch in position 21, a circuit is now established for the downdrive magnet 376 of the district selector switch, which may be traced from grounded battery 65 through the winding of magnet 376, con-

ductor 377, the position 21 contact with which wiper 247 is in engagement, wiper 247, conductor 248, and thence to ground at the upper left-hand contact of sequence switch cam 315. The downdrive magnet 70 75 80 85 90 95 100 105 110 115 120 125 130

376, upon being energized, presses the depending portion of the switch shaft 339 against the constantly rotating downdrive drum 378, whereby the switch shaft is driven downwardly into normal position. When the switch shaft reaches its normal position the brush 347 engages the normal segment 379 of the switch commutator and a circuit is established for advancing the steering switch into normal position. This circuit may be traced from ground through the armature contacts and winding of magnet 230, wiper 231, position 21 contact with which the wiper 231 is in engagement, position 21 contact with which the wiper 266 engages, wiper 266, conductor 267, normal segment 379, brush 347, conductor 344, and thence to ground at the upper contact of sequence switch cam 314 (9 to 7). With the steering switch in normal position a circuit is now established for driving sequence switch 300 into normal position which may be traced from grounded battery through the magnet winding of sequence switch 300, conductor 330, the lower left-hand contact of sequence switch cam 306, (5 to 18) conductor 380, the normal or No. 1 contact with which wiper 266 of the steering switch is in engagement, wiper 266, conductor 267, normal segment 379, brush 347, conductor 344, and thence to ground at the upper contact of sequence switch cam 314. 95 100 105 110 115 120 125

When sequence switch 300 leaves position 17 the holding circuit previously traced through the winding of relay 200 and the winding of the cut-off relay 102 of the subscriber's individual switch is opened and these relays become deenergized. The deenergization of relay 102 establishes a circuit for the stepping magnet 105 of the line switch 100 and magnet 105 becomes intermittently energized to advance the wipers of switch 100 on around to normal position. The circuit of magnet 105 may be traced from grounded battery through the winding of the magnet, its armature contacts, conductor 106, the lowermost armature and back contact of relay 102, the right-hand armature and back contact of relay 101, wiper 112, and thence to ground on segment 125. When the switch reaches normal position the wiper 112 leaves segment 125 and the circuit of magnet 105 is thereby opened to arrest the forward movement of the switch. The subscriber's line switch and the district selector, which were employed together with the circuits associated with them, are now in normal condition. 130

As soon as sequence switch 300 of the dis-

- strict selector leaves position $14\frac{1}{2}$, the circuit previously traced extending through the test brush 353, bank terminal 357, the upper contact of sequence switch cam 407, conductor 427, the outer left-hand armature and front contact of relay 421, the upper left-hand contact of sequence switch cam 409, the armature and back contact of relay 455, and through the winding of relay 421 to battery and ground and over which circuit the relay 421 of the incoming selector switch has been maintained energized, is broken at sequence switch cam 315 and relay 421 deenergizes. Upon the deenergization of relay 421 busy ground potential is connected to the sleeve conductor 464 over the upper contact of sequence switch cam 407, conductor 427, the outer left-hand armature and back contact of relay 421, and through the upper left-hand and lower right-hand contacts of sequence switch cam 411, for preventing the seizure of the trunk extending to the incoming selector switch until the selector switch has been completely restored to normal. At its inner left-hand armature and back contact relay 421 closes a circuit extending through the upper left-hand contact of sequence switch cam 406 for driving sequence switch 400 out of position 16 and into position 18. As soon as sequence switch 400 reaches position 18 a circuit is closed through the winding of the downdrive magnet 461, extending from grounded battery through the winding of magnet 461, and thence to ground through the right-hand contacts of sequence switch cam 410. Magnet 461, upon energizing, presses the depending portion of the switch shaft 432 against the constantly rotating downdrive drum 462, thereby restoring the switch shaft to normal position. As soon as the switch shaft reaches its normal position, a circuit is closed for driving sequence switch 400 out of position 18 and into position 1. This circuit may be traced from grounded battery through the winding of magnet 400, the upper right-hand contact of sequence switch cam 406, (3 to 18) normal segment 463 of the commutator 435, brush 441, conductor 437, and thence to ground through the lower contact of sequence switch cam 410. As soon as sequence switch 400 leaves position 18 the circuit of the downdrive magnet 461 is opened to arrest the downward movement of the switch shaft and the busy ground potential is removed from the sleeve conductor 464 of trunk 419 and 420. When sequence switch 400 of the incoming selector switch leaves position $16\frac{1}{4}$, the circuit previously traced through the contacts of sequence switch cam 412 over brush 442 and terminal 451 of the incoming selector, sleeve conductor 525, the left-hand armature and front contact of relay 521, the armature and back contact of relay 524, and through

the left-hand winding of relay 521, over which circuit relay 521 has been held energized, is opened and relay 521, upon deenergizing, closes a circuit for energizing relay 518. This latter circuit may be traced from grounded battery through the left-hand winding of relay 518, the upper contacts of sequence switch cam 509, and thence to ground at the right-hand armature and back contact of relay 521. Relay 518, upon energizing, closes a circuit for driving sequence switch 500 out of position 15 and into position 16. This circuit may be traced from grounded battery through the magnet 500, the lower right-hand contact of sequence switch cam 512, the left-hand armature and front contact of relay 518, and thence to ground at the upper right-hand contact of relay 508. When the sequence switch 500 leaves position 15, the previously traced energizing circuit of relay 518 is opened but relay 518 maintains itself locked up over a circuit extending from grounded battery through the left-hand contact of sequence switch cam 504, the right-hand winding of relay 518, the lower contact of sequence switch cam 510, the right-hand armature and front contact of relay 518, the lower left-hand and upper right-hand contacts of sequence switch cam 505, brush 553, the bank terminal 557, over the called subscriber's line loop, the bank terminal 559 and brush 552 of the final selector switch, the lower right-hand contact of sequence switch cam 502, and thence to ground at the upper left-hand contact of sequence switch cam 503 (15 $\frac{3}{4}$ to 16). This locking circuit for relay 518 is maintained until the called subscriber restores his receiver to its switchhook and the restoration of the final selector does not take place until the called subscriber has so restored his receiver.

In order to render the relay 518 more sensitive for releasing upon the restoration of the called subscriber's receiver to its switchhook, a shunt path is closed around the winding of relay 518 from grounded battery through the resistance element 560, and through the contact of sequence switch cam 516, which is closed in position 16.

When the called subscriber does restore his receiver to its switchhook relay 518 becomes deenergized, and at its left-hand armature and back contact closes a circuit for driving sequence switch 500 out of position 16 and into position 17. This circuit may be traced from grounded battery through the winding of sequence switch magnet 500, the upper right-hand contact of sequence switch cam 512, (16) the left-hand armature and back contact of relay 518, and thence to ground at the upper contact of sequence switch cam 508. Upon reaching position 17 sequence switch 500 is driven into position

18 over a circuit extending through its magnet winding, the lower right-hand and upper left-hand contacts of sequence switch cam 509, and to ground at the right-hand armature and back contact of relay 521. When sequence switch 500 reaches position 18 a circuit is closed for the downdrive magnet 544 extending from grounded battery through the winding of magnet 544, the 5 lower right-hand contact of sequence switch cam 511 (18), the upper right-hand contact of sequence switch cam 507 (18), and thence to ground through the upper left-hand contact of sequence switch cam 506. As soon as 10 switch shaft 527 reaches normal position a circuit is closed for driving sequence switch 500 out of position 18 and into position 1, this circuit extending from grounded battery through the winding of magnet 500, the 15 upper left-hand contact of sequence switch cam 512, (18) conductor 546, normal segment 547 of commutator 531, brush 538, conductor 533, and thence to ground at the 20 upper left-hand contact of sequence switch cam 506. The final selector and its associated circuits are now in their normal position. During the restoration of the final selector the trunk extending to the multiple terminals of the banks of all incoming 25 selector switches having access thereto is held busy by ground potential connected to the sleeve conductor 525 of the trunk over the left-hand armature and back contact of relay 521 and the upper left-hand contact of sequence switch cam 514. (2 to 18). All 30 apparatus which has been employed in the connection has now been restored to normal position and may be used for establishing other calls.

40 *No outgoing trunks available at district selector.*

If during the hunting movement of the 45 district selector switch with sequence switch 300 in position 8, the switch fails to find an idle trunk in the selected group and moves to the overflow position, the shunt circuit previously traced through the winding of relay 327 is opened and relay 327 becomes 50 deenergized, opening the circuit of updrive magnet 338 and establishes the previously traced circuit for driving the sequence switch 300 out of position 8 and into position 9. In position 9 relay 327 becomes 55 energized over a local circuit extending through its right-hand winding, the upper left-hand contact of sequence switch cam 304, the right-hand contacts of sequence switch cam 305 and the armature and front 60 contact of relay 365, and closes, at its inner right-hand armature and front contact, a circuit for driving sequence switch 300 out of position 9 and into position 10. In position 10 relay 327 is maintained energized 65 over the previously traced circuit. A cir-

cuit is now established for driving sequence switch 300 out of position 10 and into position 11, which circuit may be traced from grounded battery through the winding of sequence switch magnet 300, the lower left-hand and upper right-hand contacts of sequence switch cam 311, commutator segment 342, brush 341, conductor 344, and thence to ground through the upper contact of sequence switch cam 314. When sequence switch 300 reaches position 11 a circuit is established for relay 327 which may be traced from grounded battery through the left-hand winding of relay 327, the upper 70 right-hand contact of sequence switch cam 310 (11), the upper right-hand contact of sequence switch cam 311 (10 to 14), conductor 343, commutator segment 342, brush 341, conductor 344, and thence to ground through the upper contact of sequence switch cam 314. The steering switch has at this time positioned its wipers on the No. 7 contacts of its banks and, in the manner previously described, a circuit is established through the inner right-hand armature and front contact of relay 327 for driving sequence switch 300 out of position 11. When the sequence switch leaves position 11 the energizing circuit of relay 327 previously traced is opened at the upper right-hand contact of sequence switch cam 310, but relay 327 is maintained locked up over its left-hand armature and front contact and the upper left-hand contact of sequence switch cam 310 (11 to 15), to ground at the contact of sequence switch cam 314 until the sequence switch advances into position 15. when the circuit of relay 327 is opened and relay 327, upon deenergizing, closes a circuit for driving sequence switch 300 into 80 position 16. This circuit may be traced from grounded battery through the driving magnet of sequence switch 300, conductor 330, the upper right-hand contact of sequence switch cam 306, (15) the inner right-hand armature and back contact of relay 327, and thence to ground through the right-hand contacts of sequence switch cam 307. 85

As previously described, when sequence switch 300 passes out of position 11 the steering switch advances to point 10, the talking position, and as sequence switch 300 passes out of position 14½ the steering switch is further advanced to position 11. 90 Since now the district selector switch has moved to its overflow position and the sequence switch 300 is standing in position 16, a circuit is established for applying tone current to the right-hand winding of repeating coil 336 from the source of tone current 381, through the left-hand contacts of sequence switch cam 319, the lower right-hand winding of repeating coil 336, the upper contact of sequence switch cam 220 (16), conductor 382, the right contacts of 95

130

sequence switch cam 317 (15 to 16), the lower left-hand and upper right-hand contacts of sequence switch cam 322, and thence to ground at the right-hand armature and 5 front contact of relay 325. This tone current is inductively transmitted over the calling subscriber's line over the circuit previously traced through the left-hand windings of repeating coil 336 the winding of super- 10 visory relay 370 and wipers 242 and 243 of the steering switch. The calling subscriber receiving this tone is apprised of the fact that it is impossible to obtain the desired connection at this time and thereupon restores his receiver to its switchhook to release the connection.

Abandonment of a call by calling subscriber.

Should the calling subscriber abandon the 20 call before the sequence switch of the district selector reaches position 6, then when sequence switch 300 reaches position 6 the circuit of stepping magnet 230 of the steering switch is closed in the manner previously 25 described but the steering switch does not advance out of its normal position until the sequence switch leaves position 7 $\frac{1}{4}$. Since the calling subscriber has abandoned the call and relay 325 has therefore opened 30 the holding circuit of sleeve relay 200, a circuit is established as soon as sequence switch 300 reaches position 7, which may be traced from ground through the right-hand armature and back contact of relay 200, the right- 35 hand contacts of sequence switch cam 323, and thence to battery and ground through the winding of downdrive magnet 376. In the manner previously described, the switch shaft is driven downwardly into normal 40 position.

When the switch shaft reaches normal position a circuit is established for advancing sequence switch 300 out of position 7. This circuit may be traced from grounded battery 45 through the driving magnet of sequence switch 300, the lower left-hand contact of sequence switch cam 306 (5 to 18), conductor 380, the position 1 contact upon which wiper 266 of the steering switch is resting, 50 wiper 266, conductor 267, normal contact 379, brush 347, conductor 344, and thence to ground at the upper contact of sequence switch cam 314. When sequence switch 300 passes through position 7 $\frac{1}{4}$, the stepping 55 magnet 230 of the steering switch releases and the steering switch moves to position 2. When sequence switch 300 reaches position 8 it advances into position 9 by reason of a circuit over the upper right-hand contact 60 of cam 306 (8), the inner right-hand armature and back contact of relay 327 and contacts of cam 307. With the steering switch in position 2 and with ground on commutator segment 379 of the district selector, 65 a circuit is closed for advancing the steering

switch to point 3, which circuit may be traced from grounded battery through the armature, contacts and winding of magnet 230, wiper 231, conductor 233, wiper 266, conductor 267, segment 379, wiper 347, conductor 344, and thence to ground through the upper contact of sequence switch cam 314. In the manner previously described the steering switch is moved from position 3 to position 4 and then from position 4 to 75 position 7 through the operation of interrupter 254.

When the steering switch reaches position 7 the sequence switch 300 is again advanced by the circuit extending, as previously 80 traced, through its winding, conductor 380, the lower left-hand contact of sequence switch cam 306, conductor 380, position 7 contact and wiper 266 of the steering switch, conductor 267, commutator segment 379, wiper 347, and thence to ground at the upper contact of sequence switch cam 314. When the sequence switch reaches position 10 $\frac{1}{2}$, the previously traced circuit through stepping magnet 230 is completed and when the sequence switch leaves position 11 $\frac{1}{4}$ the stepping magnet 230 deenergizes to advance the wipers of the steering switch from position 7 to position 8. From position 8 the wipers of the steering switch are advanced over the previously traced local circuit into position 10. When the steering switch reaches position 10, the previously traced circuit through the winding of sequence switch magnet 300 is again established and the sequence switch is advanced into position 14. In position 14 the previously traced circuit through the winding of stepping magnet 230 is again closed and the steering switch is advanced from position 10 to 90 position 11 as soon as sequence switch 300 leaves position 14 $\frac{1}{2}$.

When the steering switch leaves position 10 the circuit of sequence switch 300 is 110 opened and the sequence switch is arrested in position 15. From position 15 sequence switch 300 is advanced into position 17 over a circuit which may be traced from grounded battery through the winding of sequence switch magnet 300, the right-hand contacts of sequence switch cam 323, and thence to ground through the right-hand normally closed contacts of relay 325. As soon as sequence switch 300 reaches position 15 $\frac{3}{4}$, the circuit of stepping magnet 230 of the steering switch is again established and the wipers of the steering switch are advanced from position 11 to position 12 as soon as sequence switch 300 moves out of position 16 $\frac{1}{4}$. This advancing circuit for magnet 230 may be traced from grounded battery through wiper 228, winding of magnet 230, wiper 231, the position 11 contact with which the wiper 231 engages, conductor 233, conductor 234, and thence to ground through 120 125 130

the lower left-hand contact of sequence switch cam 314.

As soon as the steering switch reaches position 12 it immediately advances into position 20 under the control of the contact of cam 254 and the back contact and outer left-hand armature of relay 252. When the steering switch reaches position 20 a circuit is established for relay 327, which may be traced from grounded battery through the right-hand winding of relay 327, the lower left-hand contact of sequence switch cam 304, (17) wiper 247 of the steering switch, conductor 248, the lower contact of sequence switch cam 321 (16 to 18), and thence to ground at the upper contact of sequence switch cam 315. The energization of relay 327 in this circuit closes a circuit over its inner right-hand armature and front contact for advancing sequence switch 300 into position 18. In position 18 a circuit is established for advancing the steering switch out of position 20 and into position 21, which circuit may be traced from grounded battery through the armature and contacts of stepping magnet 230, wiper 231, the position 20 contact with which it is in engagement, conductor 265, and thence to ground through the lower right-hand and upper left-hand contacts of sequence switch cam 315. In position 21 a circuit is closed for advancing the steering switch to normal position, which may be traced from grounded battery through the back contact, armature and winding of magnet 230, wiper 231, position 21 contact, conductor 270, contact 271, wiper 266, conductor 267, normal commutator segment 379, brush 347, conductor 344, and thence to ground at the upper contact of sequence switch cam 314. With the steering switch in normal position a circuit is now established for advancing sequence switch 300 of the district selector from position 18 to normal position, which circuit extends from grounded battery through the winding of magnet 300, the lower left-hand contact of sequence switch cam 306, conductor 380, position 1 contact upon which the wiper 266 of the steering switch is now resting, wiper 266, conductor 267, normal commutator segment 379, brush 347, and thence to ground at the upper contact of sequence switch cam 314. The district selector is now restored to normal condition and during its restoring movement causes the release of the office sender and the release of the subscriber's line switch in substantially the same manner as previously described in connection with the release of a successful connection.

Call initiated by party B on the calling line.

Had the party B on the calling line initiated the call, the circuits would have functioned as described up to the point where

relay 249 is connected to the tip conductor of the line with steering switch RS in position 6. At the substation B the bell is connected directly from the tip side 104 of the line through a condenser to ground and, therefore, there is no effective circuit at this time for relay 249. Since relay 249 does not energize, no circuit is established for switching relay 202. From this point the circuits function to extend the desired connection to the called line in the manner previously described. If the connection is successfully established, charging relay 365 is locked energized and when the calling subscriber B restores his receiver to release the connection upon the termination of conversation and sequence switch 300 advances to position 17, a circuit is established for operating the message register 119 individual to the substation B. This circuit may be traced from booster battery 399, the lower left-hand and upper right-hand contacts of sequence switch cam 324 (17), conductor 375, the inner left-hand armature and back contact of relay 252, the inner left-hand armature, front contact and left-hand non-inductive winding of relay 200, conductor 201, the outer left-hand armature and contact of relay 365, the left-hand contact of sequence switch cam 303 (12 to 17), conductor 326, the normal contacts of the left-hand armature of switching relay 202, conductor 118, wiper 109, message register magnet 119, conductor 120, the intermediate lower armature and contact of relay 102 to ground through the upper winding of relay 102. The register 119 operates and the connection is thereafter released in the manner previously described.

While the invention has been disclosed as applied to two party subscribers' lines, the invention is equally applicable to lines equipped with more than two parties and should be so interpreted in the consideration of the annexed claims.

What is claimed is:

1. In a telephone exchange system, a calling line, a plurality of subscribers' substations on said line, a called line, automatic switching mechanism for establishing a connection between said lines, message registers associated with said calling line and individual respectively to said substations, means associated with the several substations for placing discriminatory test conditions on said calling line, means associated with said switching mechanism common to a plurality of lines and responsive to said test conditions for selecting the message register corresponding to the calling substation, and means effective following the successful establishment of the connection for operating the selected register.

2. In a telephone exchange system, a calling line, a plurality of subscribers' substations

- tions on said line, a called line, automatic switching mechanism for establishing a connection between said lines, message registers associated with the incoming end of said calling line and individual respectively to said substations, means associated with the several substations for placing discriminatory test conditions on said calling line, means associated with said switching mechanism common 10 to a plurality of lines and responsive to said test conditions for selecting the message register corresponding to the calling substation, and means effective following the successful establishment of the connection for operating 15 the selected register.
3. In a telephone exchange system, a calling line, a plurality of subscribers' substations on said line, a called line, a line switch individual to said calling line and a series of selector switches for extending a connection between said lines, message registers associated with the incoming end of said calling line and individual respectively to said substations, individual operating circuits for said 20 registers extending through wipers of said line switch to the first of said series of selector switches, means associated with the several substations for placing discriminatory test conditions on said calling line, means associated with said first selector switch responsive to said test conditions for selecting the operating circuit of the message register corresponding to the calling substation, and means effective following the 25 successful establishment of the connection for operating the selected register.
4. In a telephone exchange system, a calling line, two subscribers' substations on said line, a called line, automatic switching mechanism for establishing a connection between said lines, message registers associated with the incoming end of said calling line and individual respectively to said substations, means at one only of said substations for placing a discriminatory ground potential upon one of the conductors of the calling line, means associated with said switching mechanism common to a plurality of lines and responsive to said ground potential for selecting the message register corresponding to the calling substation, and means effective following the successful establishment of the connection for operating the selected register.
5. In a telephone exchange system, a calling line, two subscribers' substations on said line, a called line, automatic switching mechanism for establishing a connection between said lines, means at one of said substations for placing a discriminatory ground test potential upon one of the conductors of the calling line, message registers associated with the incoming end of said calling line and individual respectively to said substations, an operating circuit for said registers normally 40 arranged for association with one of said 45 registers, switching means for associating said operating circuit with said other register, a relay associated with said switching mechanism common to a plurality of lines and responsive to said test potential for operating said switching means, and means effective following the successful establishment of the connection for operating the selected register.
6. In a telephone exchange system, a calling line, a plurality of subscribers' substations on said line, a called line, automatic switching mechanism for establishing a connection between said lines, message registers associated with said calling line and individual respectively to said substations, means 50 associated with the several substations for placing discriminatory test conditions on said calling line, means associated with said switching mechanism common to a plurality of lines and responsive to said test conditions for selecting the message register corresponding to the calling substation, means operative upon the successful establishment of the connection for conditioning a selected register for operation, and means effective upon the release of the connection for operating said selected register.
7. In a telephone exchange system, a calling line, two subscribers' substations on said line, a called line, automatic switching mechanism for establishing a connection between said lines, message registers associated with the incoming end of said calling line and individual respectively to said substations, means at one of said substations for placing a discriminatory ground test potential upon one of the conductors of the calling line, means associated with said switching mechanism common to a plurality of lines and responsive to said test potential for selecting the message register corresponding to the calling substation, means operative upon the successful establishment of the connection for conditioning the selected register for operation, and means effective upon the release of the connection for operating said selected register.
8. In a telephone exchange system, a calling line, two subscribers' substations on said line, a called line, automatic switching mechanism for establishing a connection between said lines, message registers associated with the incoming end of said calling line and individual respectively to said substations, means at one of said substations for placing a discriminatory ground test potential upon one of the conductors of the calling line when the substation is calling, testing means associated with said switching mechanism common to a plurality of lines and responsive to said test potential for selecting the message register corresponding to the calling substation, means for associating said testing means with said conductor of said calling line, means operative upon the suc-

cessful establishment of the connection for conditioning the selected register for operation, and means effective upon the release of the connection for operating said selected 5 register.

9. In a telephone exchange system, a calling line, two subscribers' substations on said line, a called line, means for establishing a connection between said lines, message registers associated with the incoming end of said calling line and individual respectively to said substations, means at one of said substations for placing a discriminatory ground test potential upon one of the conductors of 10 the calling line when the substation is calling, testing means associated with said connecting means responsive either to said test potential or to an unstandard grounded condition of said line for selecting one of said 15 message registers, means operative upon the successful establishment of the connection for conditioning the selected register for operation, and means effective upon the release of the connection only when said line is in 20 a standard condition for operating said selected register.

10. In a telephone exchange system, a calling line, two subscribers' substations on said line, a called line, automatic switching mechanism for establishing a connection between said lines, message registers associated with the incoming end of said calling line and individual respectively to said substations, means at one of said substations for placing 25 a discriminatory ground test potential upon one of the conductors of the calling line when the substation is calling, testing means associated with said switching mechanism responsive either to said test potential or to an unstandard grounded condition of said line for selecting one of said message registers, means operative upon the successful 30 establishment of the connection for conditioning the selected register for operation, and means effective upon the release of the connection only when said line is in a standard condition for operating said selected register.

11. In a telephone exchange system, a calling line, two subscribers' substations on said line, a called line, automatic switching mechanism for establishing a connection between said lines, message registers associated with the incoming end of said calling line and individual respectively to said substations, means at one of said substations for placing a discriminatory ground test potential upon one of the conductors of the calling line when the substation is calling, testing 55 means associated with said switching mechanism responsive to said test potential for selecting the message register corresponding to the calling line, connecting means operative prior to the completion of the connection for associating said testing

means with said conductor of said calling line, means operative upon the successful establishment of the connection for conditioning the selected register for operation, means operative upon the restoration of the call 70 ing subscriber's receiver to its switch hook for causing the reassociation of said testing means with said calling line for detecting the unstandard condition of said line, and means operative thereafter for operating 75 said selected register only if said testing means finds said line in a standard condition.

12. In a telephone exchange system, a calling line, two subscribers' substations on said line, a called line, automatic switching mechanism for establishing a connection between said lines, message registers associated with the incoming end of said calling line and individual respectively to said substations, means at one of said substations for placing a discriminatory ground test potential upon one of the conductors of the calling line when the substation is calling, testing means associated with said switching mechanism and responsive to said test potential for selecting the message register corresponding to the calling substation, connecting means operative prior to the completion of the connection for associating 90 said testing means with said conductor of said calling line, means operative upon the successful establishment of the connection for conditioning the selected register for operation, means operative upon the restoration of the calling subscriber's receiver to its switch hook for reoperating said connecting means to reassociate said testing means with said calling line for detecting an unstandard condition of said line, and means operative thereafter for operating 95 said selected register only if said testing means finds said line in a standard condition.

13. In a telephone exchange system, a calling line, a plurality of subscribers' substations on said line, a called line, automatic switching mechanism for establishing a connection between said lines, message registers associated with said calling line and individual respectively to said substations, means associated with the several substations for placing discriminatory test conditions on said calling line, testing means associated with said switching mechanism 110 responsive to said test conditions for selecting the message register corresponding to the calling substations, means for connecting said testing means to said calling line, means for testing the sensitiveness of said testing means prior to its connection with the calling line, and means effective following the successful establishment of the connection for operating the selected register.

14. In a telephone exchange system, a

- calling line, a plurality of subscribers' substations on said line, a called line, automatic switching mechanism for establishing a connection between said lines, 5 message registers associated with said calling line and individual respectively to said substations, means associated with the several substations for placing discriminatory test conditions on said calling line, testing 10 means associated with said switching mechanism responsive to said test conditions for selecting the message register corresponding to the calling substation, means for connecting said testing means with said calling line, means for charging said calling line prior to the connection of said testing means thereto, and means effective following the 15 successful establishment of the connection for operating the selected register.
- 20 15. In a telephone exchange system, a calling line, two subscribers' substations on said line, a called line, automatic switching mechanism for establishing a connection between said lines, message registers associated 25 with the incoming end of said calling line and individual respectively to said substations, means at one of said substations for placing a discriminatory ground test potential upon one of the conductors of the 30 calling line when the substation is calling, testing means associated with said switching mechanism responsive either to said test potential or to an unstandard grounded condition of said line for selecting one of 35 said message registers, means operative upon the successful establishment of the connection for conditioning the selected register for operation, means effective upon the release of the connection only when said line 40 is found to be in a standard condition for operating said selected register, and means for operating an alarm signal if said line is found to be in an unstandard condition.
16. In a telephone exchange system, a calling line, two subscribers' substations on said line, a called line, automatic switching mechanism for establishing a connection between said lines, message registers associated 45 with the incoming end of said calling line and individual respectively to said substations, means at one of said substations for placing a discriminatory ground test potential upon one of the conductors of the calling line when the substation is calling, testing means 50 associated with said switching mechanism, means for connecting said testing means with said line during the establishment of the connection and again following the restoration of the calling subscriber's receiver to its switch hook, means operated by 55 said testing means upon its first connection to the calling line responsive to said test potential or to an unstandard condition of said line for selecting one of said registers, 60 and means operated by said testing means 65 upon its second connection to the line responsive to said unstandard condition for nullifying the selection of said register and for operating an alarm signal.
17. In a telephone exchange system, a calling line, a plurality of subscribers' substations on said line, a called line, switching means for establishing a connection between said lines, message registers associated with said calling line and individual respectively to said substations, means associated with the several substations for placing discriminatory test conditions on said calling line, and means associated with said switching means common to a plurality 70 of lines and responsive to said test conditions for selectively operating the message register corresponding to the calling substation.
18. In a telephone exchange system, a calling line, a plurality of subscribers' substations on said line, a called line, switching means for establishing a connection between said lines, message registers associated with said calling line and individual respectively 75 to said substations, means associated with the several substations for placing discriminatory test conditions on said calling line, means associated with said switching means common to a plurality of lines and responsive to said test conditions for selecting the message register corresponding to the calling substation, means operative upon the successful establishment of the connection 80 for conditioning a selected register for operation, and means effective upon the release of the connection for operating said selected register.
19. In a telephone exchange system, a calling line, a plurality of subscribers' substations on said line, a called line, switching means for establishing a connection between said lines, message registers associated with said calling line and individual respectively 85 to said substations, means associated with the several substations for placing discriminatory test conditions on said calling line, testing means associated with said switching means responsive to said test conditions for selecting the message register corresponding to the calling substation, means for connecting said testing means to said calling line, means for testing the sensitivity of said testing means prior to its connection with the calling line, and means effective following the successful establishment 90 of the connection for operating the selected register.
20. In a telephone exchange system, a calling line, a plurality of subscribers' substations on said line, a called line, switching means for establishing a connection between said lines, message registers associated with said calling line and individual respectively 95 to said substations, means associated with

the several substations for placing discriminatory test conditions on said calling line, testing means associated with said switching means responsive to said test conditions for selecting the message register corresponding to the calling substation, means for connecting said testing means with said calling line, means for charging said calling line prior to the connection of said testing means thereto, and means effective follow-

ing the successful establishment of the connection for operating the selected register.

In witness whereof, I hereunto subscribe my name this 8th day of December A. D., 1920.

15

DAWSON M. TAGGART.

In witness whereof, I hereunto subscribe my name this 4th day of December A. D., 1920.

FREDERICK J. SCUDDER.
